UNITED STATES PATENT OFFICE

HENRY W. NIEMAN, OF BETHLEHEM, PENNSYLVANIA, ASSIGNOR TO BETHLEHEM STEEL COMPANY

FIRE-CONTROL MECHANISM

Application filed June 22, 1926. Serial No. 117,735.

My invention relates to anti-aircraft fire control systems and it has for an object to provide an accurate system of fire control for anti-aircraft artillery which shall utilize apparatus which is automatic for continuously computing gun fire data and for transmitting such data to a gun or guns.

Heretofore, in so far as I am aware, anti-aircraft fire control systems have not been satisfactory owing to the "dead time" or the intervention of the human element in the train of events between the time of observing and arriving at the final data or results used in laying the gun. Owing to the fact that an aeroplane is capable of moving in any direction, fire control system for targets moving on land or on sea cannot be used. Attempts have been made to modify these systems by making altitude assumptions or corrections; however, such modifications have not proved to be satisfactory, owing to the high speed and variability of position of an aeroplane and to the fact that computing and estimating all take time, adding to the "dead time", and making the operation of such apparatus largely a matter of guess work. My system has been devised to operate along entirely different lines. First of all, it is based on the idea that the position of an aerial target may be accurately defined by a system of three coordinates. Accordingly, therefore, for example, I provide two spaced telescopes, which have aligned primary axes, the line coincident with these axes being known as the base line, and which are movable about their primary axes and about their secondary axes in order to be kept trained on the target. With alignment of the primary axes, it will be apparent that the target and the telescopes occupy a common plane, which, with motion of the aerial target other than in this instantaneous plane, results in turning of the common plane about the base line. The angle between this plane and the horizontal plane of the base line, if the latter is horizontal, is the primary angle or one of the angles used in identifying the position of the target. If the base line is not horizontal, then the plane of reference is such a plane as includes the base line and which is normal to the vertical

plane of the base line. The telescopes in moving in this way must move about secondary axes; and the angles between the lines of the telescopes passing through the target and the base line are the other two angles used, with the first angle, in identifying the instantaneous position of the target. However, it is necessary owing to movement of the target to predict continuously the coordinates of future positions as well as the corresponding times of flight for a projectile, such that the latter and the target shall reach a future position at the same time. I have, therefore, devised automatic computing mechanism near to one of the telescopes which receives the three angles from the telescopes and which determines the rates of change of three angles, two of which are the primary angle and the secondary angle of the near telescope and the third of which is the difference between the secondary angle of the far telescope and the secondary angle of the near telescope. From these factors, the computing apparatus calculates and transmits automatically and continuously azimuth and vertical angle indications together with corresponding times of flight to the gun, the time of flight at any instant being the time required for a projectile, if fired at that instant, and the target to reach simultaneously the position in space indicated at that instant by azimuth and vertical indications. In practice, the gun is kept trained continuously in accordance with the azimuth and vertical angles transmitted from the computing station, these angles determining continuously at every instant the future position which will be occupied by the target and the projectile if the latter is fired at a given instant, assuming, of course, that the target continues to move at the same velocity and in the same straight line course or in a tangent to the path of motion it had at that instant. In other words, my apparatus determines continuously the instantaneous future position of the target based on the theory that the target shall move on a tangent to the path it had at the given instant. The time of flight is utilized by the gunner in setting the fuze so that the projectile shall be caused to explode as near to the target as possible. The

apparatus is provided with manual controls whereby it may be caused to operate properly with variations in length of base line and distances of the gun or guns from the near telescope as well as with variations in tenuity of the atmosphere and windage. It is an object of my invention, therefore, to provide apparatus which shall utilize the aforementioned factors in obtaining these results.

- 10 A further object of my invention is to provide a fire control system having apparatus for determining and transmitting three instantaneous coordinates of an object moving through space together with computing mechanism which shall utilize the instantaneous coordinates and the rates of change thereof for the purpose of indicating future coordinates, one of the latter being the time of flight.
- 15 A further object of my invention is to provide a fire control system which shall include two spaced observation stations for determining three instantaneous coordinates of a moving target and a computing station together with repeating transmitting devices between the observation stations and the computing station whereby moving parts therein will be moved proportionately to movements of parts at the observation stations.
- 20 A further object of my invention is to provide two spaced telescopes and a computing apparatus together with means for transmitting to the computing apparatus the initial position and changes in position of the telescopes while the latter are kept trained on a target moving through space.

A further object of my invention is to provide a gun having vertical and azimuthal devices for training it and a fire control system for the gun including a pair of spaced telescope stations for determining the instantaneous values of three coordinates of a target moving through space and a computing mechanism which utilizes those coordinates and the rates of change thereof in automatically and continuously determining vertical and azimuth angles by which to lay the gun and the time of flight by which to set the fuze.

30 A further object of my invention is to provide, in a fire control system, a pair of spaced telescope stations with the primary axes of the telescopes aligned in a common base line and the telescopes being maintained continuously in a plane with a target by being trained thereon together with means for subtracting one angle included by the line of one telescope to the target and the base line from the angle included between the line of 35 the other telescope to the target and the base line, the angles being considered in the same sense.

A further object of my invention is to provide, in a fire control system, observation apparatus which shall transmit three angular

coordinates to computing apparatus wherein one coordinate is subtracted from another and wherein the rates of change of two of the coordinates and the rate of change of the difference between one of the latter coordinates and the third coordinate are determined.

70 A further object of my invention is to provide a fire control system which shall receive instantaneous values of three coordinates and from the instantaneous values of these and their rates of change shall determine the "future" coordinates of a target together with apparatus which shall transform the immediately determined coordinates into azimuth and vertical angles suitable for laying a gun.

75 A further object of my invention is to provide mechanical fire control apparatus which receives the instantaneous values of spherical coordinates of a target moving through space and which receives a manually applied correction for tenuity of the atmosphere and from these factors determines mechanically and continuously the time of flight and azimuth angle corrected for drift, and vertical angle corrected for super-elevation for laying a gun, such that if the gun is continuously kept at positions determined by the azimuth and vertical angles the projectile 80 will reach the same point in space simultaneously with the target, assuming that the target continues to move at uniform velocity and in a path which is tangent to the direction it had when the projectile was fired.

85 A further object of my invention is to provide a fire control system which includes apparatus for determining the logarithm of the future range of a target moving through space together with means for determining from this logarithm the horizontal time of flight and together with other means for determining and adding corrections for the angle inclination and for tenuity of the atmosphere in order to determine the true time 90 of flight for inclined fire.

95 A further object of my invention is to provide apparatus for determining the "future" range of a target together with the "future" vertical range together with other apparatus for finding the angle of super-elevation to be added to the "future" angle determined by the first apparatus, the second apparatus utilizing a function of the future range, a function of the determined vertical angle and a 100 manual setting for tenuity of the atmosphere in determining the super-elevation to be added to the already determined vertical angle.

105 A further object of my invention is to provide, in fire control apparatus, means for determining the product of the time of flight by the rate of change of angular or spherical coordinates.

110 A further object of my invention is to pro-

vide a coordinate transformer including "input" apparatus which receives coordinates in accordance with one system, thereby causing a line in the input system to represent the direction in space indicated by the supplied coordinates and an "output" vertical and azimuth system whose movements in the vertical and in azimuth are derived from movement of said line.

10 A further object of my invention is to provide a fire control system having two spaced telescope stations, a gun near to one of the stations, and a computing station which receives continuously instantaneous target position data and which from the received data calculates continuously and automatically data for a gunner and which automatically and continuously corrects the data for parallax due to the distance between the near station and the gun.

Apparatus involving the principles of my invention is illustrated in the accompanying drawings, forming a part of this application, in which:

25 Figs. 1 and 2 are diagrammatic views showing the arrangement and application of my improved fire control system;

Attention is called to the large underlined numerals in Figs. 1, 2 and other assembly drawings which serve to identify corresponding groups of mechanism in partial assembly drawings.

120 In general, my anti-aircraft fire control system includes two observation stations indicated at 10 and 11, Fig. 1, one of which, for example, 10, is assumed to be nearer to the gun, at 12, than the other. The stations, at 10 and 11, include telescopes 13 and 14, respectively, the telescopes being so arranged

125 13.

that their primary axes of revolution 15 and 16, are in the same base line B (see Fig. 2), while the secondary axes 17 and 18 of the respective telescopes are arranged at right angles to the base line B. As the primary axes 15 and 16 are in the same straight line, the primary angle α will be the same for each of the telescopes. The secondary angles, ρ of the telescope 13 and ρ_1 of the telescope 14, and their relationship to each other constitute a measure of the inclined range R.

With the training of the telescopes 13 and 14 on a target moving through space, such as an aeroplane, diagrammatically indicated in Fig. 2, the primary angle α is continuously transmitted to computing mechanism at 20 by any suitable telemetric device 21, including, for example, a primary motor device 22 and conductors 22' leading to a secondary motor device in the computing mechanism, at 20. The secondary angles ρ and ρ_1 are transmitted, respectively, from the axes 17 and 18 by telemetric devices, at 23 and 24, including, for example, primary motor devices 25 and 26 connected, respectively, by conductors 27 and 28 to motor devices of the computing mechanism, at 20.

The computing mechanism, at 20, is located near to the gun or guns, at 12. The three angles α , ρ , and ρ_1 are transmitted to the computing mechanism, at 20, which determines the rates of change of these angles; actually, however, the rate of change of ρ_1 is not determined but instead the rate of change of λ which is equal to $\rho_1 - \rho$. From these three angles, α , ρ , and λ , the rates of change thereof, and from certain additional data, hereinafter referred to, the mechanism, at 20, operates continuously to compute the proper azimuth and vertical angles by which to lay the gun and the time of flight by which to set the fuze. These angles and the determined times of flight are transmitted electrically and continuously to the gun, the azimuth and vertical angles being transmitted by conductors 30 and 31 to the azimuth and vertical devices 32 and 33 and the time of flight being transmitted by conductors 34 to the time of flight indicator, at 35. The "time of flight" is used in the usual manner for fuze setting while the devices 32 and 33 are preferably of the follow-the-pointer or equivalent type so that the gun is always correctly aimed for scoring a hit, provided, of course, that the setting of the fuze and the indication of the indicator 35 correspond.

For making the prediction for future position, the mechanism is designed on the assumption that the target continues on the same straight line course, and at the same velocity during the time of flight of the projectile as it had at the instant of firing of the gun.

The standard base line is preferably about 2000 feet, but it may be more or less provided

the distance is accurately measured and the computing mechanism adjusted accordingly as hereinafter referred to. The base line B may be horizontal or inclined at any angle necessitated by the topography; however, if this line is inclined, the primary axes 15 and 16 of the telescopes will also be inclined and it is necessary to know the inclination in order that the computing mechanism may be suitably adjusted, as hereinafter referred to. The gun or guns, at 12, may be, for example 150 to 300 feet from the near station at 10, providing the exact distance is measured and the magnitude utilized in the manner herein-after set forth.

In general, for the present, the telescopes have been sufficiently described, and the computing mechanism will now be referred to in a general way after which the complete apparatus will be taken up for more detailed discussion. Referring to Fig. 2, it will be seen that the computing mechanism, at 20, comprises five interrelated parts, (1) comparators 126, (2) range and position apparatus 127, (3) prediction mechanism 129, (4) transformer of coordinates device 130, and (5) ballistic mechanism 128.

The primary angle α is transmitted by the telemetric device, at 21, to the comparators, while the secondary angles ρ and ρ_1 are transmitted by the telemetric devices, at 23 and 24, respectively, to the range and position apparatus, wherein, among other things, the angle $\lambda = \rho_1 - \rho$ is determined and transmitted to the comparators.

The comparators determine the product of the rates of change of the angles α , ρ , and λ by the time of flight T of the projectile, this time of flight T coming from the ballistic mech-

anism. The quantities $T \frac{d\alpha}{dt}$, $T \frac{d\rho}{dt}$, and $T \frac{d\lambda}{dt}$ are transmitted to the prediction mechanism.

Range and position apparatus.—As already pointed out, the secondary angles ρ and ρ_1 are received directly by the range and position apparatus. The angle ρ is subtracted and the difference λ , is transmitted to the comparators. In addition to this, these angles ρ and ρ_1 are utilized in this apparatus in the calculation of

(1) the $\log_{10}$ of the present inclined range R_0 , and
(2) certain mathematical expressions

$\log_{10} (\cot \lambda - \cot \rho_1)$ and
 $\cot \rho + \cot \rho_1$

all of which are transmitted to the prediction mechanism.

The prediction mechanism receives the following quantities:

(1) the angle ρ by direct connection,
(2) the present range $\log_{10} R_0$ and the quantities $\log_{10} (\cot \lambda - \cot \rho_1)$ and $\cot$

$\rho + \cot \rho_1$ from the range and position apparatus, and

(3) the rates of change $T \frac{d\alpha}{dt}$, $T \frac{d\rho}{dt}$, and
 $T \frac{d\lambda}{dt}$ from the comparators.

In addition to these calculated quantities received from the range and position apparatus and from the comparators, adjustments are made for the length of base line B and for the distance G from the center of the gun position to the near telescope. From the factors ρ , $\log_{10} (\cot \lambda - \cot \rho_1)$, $\cot \rho + \cot \rho_1$, $T \frac{d\alpha}{dt}$, $T \frac{d\rho}{dt}$, $T \frac{d\lambda}{dt}$, B, and G, the range and position apparatus calculates the following quantities:

1 (1) The $\log_{10}$ of the future range R_g of the
 20 target, that is, the "range" to the future po-
 sition the target will occupy after a time in-
 terval T (the time of flight of the projectile),
 this being corrected for parallax error due
 25 to the difference in position of the gun or guns
 and the near telescope, this quantity being
 transmitted to the ballistic mechanism:

- (2) the "future" secondary angle ρ' ;
- (3) the difference between the present and

(4) the difference between the present and future primary angles ϕ ; and
 30 (4) the parallax correction for the future secondary angle θ .

The quantities ρ' , ϕ , and θ are transmitted to the transformer of coordinates device.

The transformer of coordinates device receives the present primary angle α , by direct connection, and the quantities ρ' , ϕ , and θ from the prediction mechanism; and, from these, it calculates the vertical angle η and azimuth angle ν of the future line of sight measured from the gun; and, these quantities η (vertical) and ν (azimuth) are transmitted to the ballistic mechanism.

45 to the ballistic mechanism.

The ballistic mechanism receives

- (1) the $\log_{10}$ of the "future" range R_g , (including the parallax correction), from the prediction mechanism;
- (2) the future vertical angle η and the future azimuth ν from the transformer of co-ordinates device;
- 50 (3) the tenuity of the atmosphere, for which there is a manual setting; and
- (4) the wind corrections to vertical angle η and to the azimuth angle ν which are either received from a mechanical wind computer or set off manually.

From these quantities, the ballistic mechanism calculates

(1) the square root of the time of flight
 $\sqrt{T}$:

60 (2) the angle of superelevation " s ", which, together with a wind correction it adds to the vertical angle η of the line of sight; and (3) the angle of drift " γ ", which it adds

(3) the angle of drift " d " which it adds to the azimuth angle v , which is also adjusted for wind.

The quantity $\sqrt{T}$ is transmitted mechanically to the comparators and electrically to the gun or guns to the time of flight device 35 (see Fig. 1). The vertical angle η , corrected for the angle of super-elevation " s " and for wind is transmitted electrically by the conductors 31 to the vertical gun pointing device 33; and the azimuth angle ν , corrected for drift " d " and for wind, is transmitted electrically to the azimuth gun pointing device 32. 75

In brief then, angular movements are transmitted from the telescopes, at 10 and 11, to the comparators and to the range and position apparatus, the comparators determining $T \frac{d\alpha}{dt}$, $T \frac{dp}{dt}$, and $T \frac{d\lambda}{dt}$, which are transmitted to the prediction mechanism, and the range and position apparatus determines the $\log_{10}$ present inclined range R_0 and the quantities $\log_{10} (\cot \lambda - \cot \rho_1)$ and $\cot \rho_1 + \cot \lambda$, all of which are transmitted to the prediction mechanism. The prediction mechanism receives these quantities $T \frac{d\alpha}{dt}$, 90

$T \frac{d\rho}{dt}$, $T \frac{d\lambda}{dt}$, (from the comparators) and $\log_{10}$ at
 $(\cot \lambda - \cot \rho_1)$, $\cot \rho + \cot \rho_1$, and the present
range $\log_{10} R_0$ together with the present
value of ρ and corrections are made for the
length of the base line B and for the distance
of the gun to the near station 10. The pre- 95

of the gun to the near station 10. The prediction mechanism calculates the future range $\log_{10} R_g$, which is transmitted to the ballistic mechanism, and it calculates the "future" secondary angle ρ' , the difference between the present and future primary angles ϕ , and the parallax correction θ , which are transmitted to the transformer of coordinates device. The transformer of coordinates device determines the vertical angle

ordinates device determines the vertical angle η and the azimuth angle ν from the present value of α and from the quantities ρ' , ϕ and θ and transmits these quantities to the ballistic mechanism. The ballistic mechanism receives the future range $\log_{10} R_g$ from the prediction mechanism and the angles η and ν from the transformer of coordinates device, makes corrections for super-elevation and windage to the vertical angle η , makes a drift correction to the angle ν , and determines $\sqrt{T}$, the corrected values of η and ν being transmitted to the gun and $\sqrt{T}$ being transmitted to the comparators and to the gun.

Referring now to the apparatus more in detail, the telescopes will first be described. In Figs. 3, 4, 5, 6 and 7, I show the near station telescope 13 set up for the measurement and transmission of the angles α and ρ . This telescope is carried by a supporting bracket 36 having a bottom flange portion 37 which rests on a table 38, the flange 37 having a central opening through which extends the post 39 threaded to receive the nut 40. By loosen- 125

ing the nut 40, the U-shaped supporting bracket 36 may be adjusted about a vertical axis and then secured in a desired position by tightening the nut 40 (see Fig. 7).

5 The table 38 is carried by a support 42, the latter being provided with a central downwardly-facing socket 43 to receive a spherically-faced member 44 carried by the depending stem 45 of the table. The table also 10 carries three leveling screws 46 by which it may be levelled. The supporting structure is carried by a control box 47, which, in turn, is supported by the tripod legs 48.

Referring now to Figs. 5 and 6, the telescope 13 includes an eye-piece 50 carried by a gimbal frame 51 pivoted at 52 and 53 to the uprights of the U-shaped support 36. The telescope carries at its outer end a prism 54 having a face 55 parallel to the face 56 of a 20 prism 57 having a surface 58 against which light normally strikes. The prism 57 is carried by a U-shaped frame 60 pivotally mounted at 61 and 62 to the gimbal frame 51, the axis of the bearings 52 and 53 being at right 25 angles to the axis of the bearings 61 and 62. Since the prism 57 is capable of moving about right-angular axes, it may be turned toward any point in the heavens.

The frame 51 is turned by a power shaft 30 63 coming from the control box 47, such shaft having a coupling connection 64 which permits of angular movement with respect thereto of an upper shaft section 65 journaled in bearings 66 of bracket 67 carried by the support 36. The shaft section 65 carries a worm 68 which meshes with the sector 70 connected to the gimbal frame 51.

The inner U-shaped frame 60 is turned by a power shaft 71 coming from the control box 40 47, the shaft 71 being connected by the coupling 72 to the shaft section 73 journaled in bearings 74 carried by the bracket structure 67. The shaft section 73 has a worm 75 thereon meshing with the gear 76, carried 45 by the shaft 77, which extends through the journal of the frame 51 in the bearings 53 and has a bevel gear 78 meshing with a bevel gear 80 carried by the cross shaft 81, the latter having, at its other end, a pinion 82 which meshes 50 with the double gear 83, the latter meshing with the sector 84 carried by the U-shaped frame 60. The shaft sections 65 and 73 are connected, respectively, to initial elements of telemetric devices, such as the "Selsyn" 55 motor devices 85 and 86.

From the foregoing, it will be apparent that the shafts 63 and 71 may be actuated to cause the prism 57 to follow any point in the heavens, movement imparted by the shaft 63 60 resulting in tilting of the frame 51 about the axis of the bearings 52 and 53, (α movement) and movement imparted by the shaft 71 resulting in tilting of the inner U-shaped frame about the axis of its bearings 61 and 62 65 (ρ or ρ_1 movement). The power shafts 63

and 71 are actuated by mechanism in the box 47.

The control box 47 is provided with operating handles 88, 89, 90 and 91, whereby the shafts 63 and 71 may be operated to turn the frame 51 about the primary, or α , axis and the inside frame 60 about the secondary, or ρ , axis, the handle or handwheel 88 being connected through high speed or low speed frictional gearing to the shaft 71, the handwheel 75 89 controlling the ratio of the low-speed frictional gearing and the handle 90 controlling the shift from high to low speed and vice versa. The handwheel 91 is directly connected through gearing to α shaft 63.

Referring to the gearing in the box 47 between the handwheel 88 and the shaft 71, it will be seen from Fig. 9 that the handwheel is connected to a shaft 92 carrying a spur gear 93, which meshes with the pinion 94 on the shaft 95 carrying a fly-wheel 96 having a friction face 97 engaged by the transversely shiftable friction wheel 98 splined to the shaft 99, which is directly connected to α shaft 71 going to the telescope. The friction wheel 98 is engaged by a yoke 100 pivotally connected to a sleeve 101 and the latter is threaded to a shaft 102. The shaft 102 may be turned in either direction by the handwheel 89, acting through the intermediary of the sprocket 95 103, the chain 104, the sprocket 105, and the bevel gearing 106. The pivotal connection between the yoke 100 and the sleeve 101 serves to permit of the friction wheel 98 being moved toward and away from the friction face 97; and a spring 107 is disposed between the yoke 100 and the sleeve 101 to bias the friction wheel 98 toward the friction face 97 so that a desired pressure between these parts may be had.

If it is desired to operate the shaft 71 faster, as when first training the telescope on the target, this may be done by disengaging the frictional gearing and engaging spur gearing between the handwheel 88 and the shaft 71. The disengagement of the frictional gearing is effected by the handwheel 90, which operates a cam 108 to oscillate an arm 110, the latter being connected to a shaft 111, carrying upper and lower arms 112 and 113. The upper arm 112 is connected by means of a yoke and collar to a shaft 114, which bears a spur pinion 115 at one end adapted to mesh with the gear 93 and a bevel gear 116 at the other end adapted to mesh with the bevel pinion 117 connected to the shaft 99. The shaft 99 is connected to the shaft 71 by a flexible or universal joint 118 so that it may be swung toward and from the friction face 97. When the shaft 111 is rotated to swing the shaft 99 away from the friction surface 97 by means of the lower arm 113, to disengage the friction pinion, the upper arm 112 moves the shaft 114 longitudinally to engage the pinion 115 with the gear 93 and the bevel gear 116 115 120 125 130

with the bevel gear 117, whereupon the shaft 71 may be operated from the handwheel 88 through the spur and bevel gearing to secure rapid training movement. With disengagement of the spur gearing and engagement of the friction gearing, relative speed of the shaft 99 to handwheel 89 may be varied from zero to the permissible maximum through infinite gradations.

10 The shaft 63 is operated from the handwheel 91, the latter being connected to a sprocket 120 engaging a chain 121, which passes over a sprocket 122 connected to a shaft 123 to drive a bevel pinion 124 meshing with a bevel gear 125, which, in turn, is connected to the shaft 63.

15 The two telescopes are operated from their control boxes and the primary angle α and the secondary angles ρ and ρ_1 are transmitted telemetrically, as indicated in Figs. 1 and 2, to the computing station at 20.

20 Referring to Fig. 2, it will be seen that the angle α enters the comparators while ρ and ρ_1 enter the range and position apparatus. 25 The range and position apparatus and the comparators serve to determine certain mathematical factors which are transmitted and utilized in a manner to be described in the prediction or calculating mechanism.

30 The comparators serve to determine the rates of change of the angular coordinates; however, the angle ρ_1 is not used but instead the angle λ which is equal to $\rho_1 - \rho$. The angle α , therefore, enters the comparators, at 35 126, and the angles ρ and λ enter the comparators from the range and position apparatus 127. The comparators first determine

the three products of rates of change $T \frac{d\alpha}{dt}$,

40 $T \frac{d\rho}{dt}$, and $T \frac{d\lambda}{dt}$, the quantity $\sqrt{T}$ coming from the ballistic mechanism 128. The quantities $T \frac{d\alpha}{dt}$, $T \frac{d\rho}{dt}$, and $T \frac{d\lambda}{dt}$ are transmitted to 45 the prediction mechanism 129. The angle α is also transmitted to the transformer of coordinates device and angle ρ is also transmitted to the range and position apparatus and to the prediction mechanism as herein- 50 after pointed out.

Considering now the comparators more in detail, I show comparators at 131, 132 and 133 (see Figs. 10^b, 11 and 11^a) which are adapted to determine, respectively, the quantities $T \frac{d\lambda}{dt}$, $T \frac{d\alpha}{dt}$ and $T \frac{d\rho}{dt}$. The angle λ is transmitted by a shaft 134 coming from the range and position mechanism 127; the angle α is transmitted directly to the comparator, at 55 132, from the α telemotor 135 connected by conductors 22' to the near station telescope telemotor 22, the motor 135 driving the comparator through a shaft 136; and the angle ρ is transmitted from the ρ telemotor 137, its shaft 138, bevel gears 139 and 140, and shaft

142 to the comparator at 133. The quantity $\sqrt{T}$ is transmitted from the ballistic mechanism 128 by means of a shaft 143, which is geared to one end of the shaft 144, the other end of the latter shaft being connected by 70 means of sprocket gearing 145 and 146 to the shafts 147 and 148 of the comparators, at 131 and 132, respectively. The shaft 148 is connected by sprocket gearing 149 to the shaft 151 of the comparator at 133. Hence it will 75 be apparent that the shafts 147, 148, and 151 are driven as $\sqrt{T}$.

The comparators are similar in construction and in modes of operation; and, therefore, a description and illustration of one, namely, the comparator, at 131, will suffice for all. This comparator includes a friction disk 152 which is connected underneath (Figs. 10^b and 11) by bevel gearing 153 to λ shaft 134 so that the rate of rotation of the friction disk is proportional to the rate of change of λ , or $\frac{d\lambda}{dt}$. Fig. 11^a shows a section in elevation of comparator 132 which, with the exception of the gearing driving the friction disk, is similar to comparator 131. In this view parts identical with parts shown in plan Fig. 11 are similarly numbered, prime figures being used, however, in this case. The disk 152 engages a friction wheel 154 which is splined to a shaft 155 and which is shiftable diametrically of the disk 152 by means of a yoke 156 having a nut portion 157 which engages threads 158 of the shaft 147. Since the threads 158 are uniform, the position of the yoke 156, and consequently of the friction wheel 154, will be proportional to $\sqrt{T}$ measured from a zero position. If this zero position was made the center of the disk 152, then, since the rate of rotation of the disk is proportional to the rate of change of λ , the rotational velocity of the wheel 154 would be proportional to this multiplied by $\sqrt{T}$. This could be transmitted by direct connection to the universal 160; however, such an arrangement, although simple, is not convenient, since, to obtain a travel of the wheel 154 radially of a disk 152 large enough to be set off with accuracy, a disk of considerable size 115 would be necessary. I, therefore, provide a gearing arrangement in which the full diameter, instead of the radius, may be utilized. To this end, I show differential gearing at 161, whose pinion carrier 162 has a bevel gear 163 thereon meshing with the beveled toothed rim 164 of the disk 152. Hence, the pinion carrier 162 and the pinions 165 will move orbitally in proportion to the rate of change of λ . The pinions 165 are engaged at one side by a bevel gear 166, which is keyed to the shaft 155, and, at the other side, by a bevel gear 167, which is keyed to the shaft 168 connected to the universal joint 160. Hence it will be seen that, instead of simple 120

frictional gearing being used as the transmission medium, I use a differential one of whose three principal elements is controlled by frictional gearing.

5 With this arrangement the rotation transmitted from disk 152 to shaft 168 will be the sum of that due to the roller 154 and that due to the rotation of the pinion carrier 162. The law for an ordinary bevel differential such as here shown is that $V_A = 2V_B - V_C$, where V_A = velocity of one of the end bevel gears, V_C that of the other, and V_B the velocity of the pinion carrier, all about the common axis. In this case let the velocities of 10 168 = V_A , of 155 = V_C and of 162 = V_B . Further let the velocity of plate 152 = V_D . Now the relative velocity between output shaft 168 and plate 152 is: $\frac{V_A}{V_D} = \frac{2V_B}{V_D} - \frac{V_C}{V_D}$. Since the 15 ratio between V_B and V_D is constant as determined by gears 163 and 164, which ratio we will call G , the formula reduces to $\frac{V_A}{V_D} = 2G - \frac{V_C}{V_D}$. The ratio $\frac{V_C}{V_D}$ is equal to the 20 25 ratio between the radius of roller 154 and the radius from the center of the plate to the point of contact with the roller, and may be plus or minus in sign according to whether the roller is contacting on the lower or upper half of the plate. If $\frac{V_C}{V_D} = 2G$, $\frac{V_A}{V_D} = 0$ and this condition, which is nearly that illustrated in Fig. 11 corresponds to the value, $\sqrt{T} = 0$. 30 35 As this zero position is at the edge of the plate no negative values of $\sqrt{T}$ can be represented, all other radial positions of the roller corresponding to positive values of $\sqrt{T}$, which is a maximum when the roller is at a position diametrically opposite to that shown. In the 40 45 actual device it is not intended to represent $\sqrt{T} = 0$ since T is never less than a definite value, say 1 second. Therefore the dimensions of plate, roller and gearing are chosen as so to bring this minimum value at one edge of the plate, and the whole diameter of the plate is then available for setting off values from this minimum value to any chosen maximum. Aside from this manner of setting off 50 55 $\sqrt{T}$ and certain mechanical advantages obtained by this form of variable speed mechanism, it is entirely equivalent to a simple roller and disk and performs the function of obtaining any desired speed ratio between the plate and output shaft.

The universal joint construction 160 connects the shaft 168 to a friction roller 170 which rotates at a speed proportional to $\sqrt{T} \frac{d\lambda}{dt}$. The roller 170 is journaled in a frame 171 pivoted at 172. The roller 170 engages tangentially and transversely with a roller 173.

60 65 The roller 173 rotates as a resultant effect of the constant speed motor 174 and the $\sqrt{T}$

shaft 144; and the purpose of this combination is to furnish to the roller 173 a speed proportional to $\frac{1}{\sqrt{T}}$ which upon mechanical comparison with speed of the roller 170, $\sqrt{T} \frac{d\lambda}{dt}$ yields the product $T \frac{d\lambda}{dt}$ and the displacement of the frame 171 is a function of that product. To this end, I show a constant speed motor 174 connected to a shaft 175 by gearing 176. The shaft 175 is connected to a disk 177 by means of a differential at 178, which is similar to the differential 161, and this differential includes a bevel gear 180, connected to the shaft 175, pinions 181, which are supported by a carrier 182 having a bevel gear 183 thereon, which meshes with the bevel gear 184 on the disk 177, and a bevel gear 185, which is connected to one end of the shaft 186. A friction wheel 187 is splined on the shaft 186 and it is shiftable therealong by means of a yoke 188 having a nut portion 190 engaging threads 191 on shaft 144. The position of the friction wheel 187 is dependent upon $\sqrt{T}$. The disk 177 has a spur gear portion 193 which meshes with a pinion 194 carried by the shaft 195 upon which the roller 173 is mounted. The mechanism just described is similar in every way to the mechanism between plate 152 and output shaft 168. Now however instead of desiring the input velocity multiplied by $\sqrt{T}$ we desire it to be divided by this quantity, therefore, the input is applied at the shaft 175 and the output is taken off at gear 193, which reverses the operation and divides by $\sqrt{T}$. Therefore the constant speed applied to shaft 175 will be transformed into a speed on gear 193 proportional to $\frac{1}{\sqrt{T}}$.

105 110 115 120 If the drum or roll 173 is rotated in the direction of the arrow (Fig. 11) and the roll 170 is stationary, the effect of the drag or friction between the rolls is to draw the roll 170 and its frame 171 about the pivot 172 of the latter to a medial position. If, however, the roller 170 also rotates in the direction of the arrow, such roller will swing away from the central position and take up an equilibrium position where the drag of the roller or drum 173 just neutralizes the rolling of the roller 170. In this position

$$\frac{V_r}{V_d} = \sin \mu$$

where

V_r = surface speed of roller 170,

V_d = surface speed of drum 173,

μ = angle of displacement of roller 170 from its central position.

The above relationship follows since the component of the surface speed of the drum at right angles to the axis of the roller is $V_d \sin \mu$ and this in turn must be equal to

Vr in order that the parts shall be in equilibrium.

Now since $Vr \propto \sqrt{T} \frac{d\lambda}{dt}$ and $Vd \propto \frac{1}{\sqrt{T}}$, sin $5 \mu \propto T \frac{d\lambda}{dt}$, that is, the sine of μ is proportional to the time of flight of the projectile times the rate of change of λ . When $\frac{d\lambda}{dt}$ is negative, μ is negative, T always being positive.

In the above mechanism the product $T \frac{d\lambda}{dt}$ 15 was found by multiplying the speed $\frac{d\lambda}{dt}$ by the factor $\sqrt{T}$ and comparing this resultant speed with a constant speed multiplied by $\frac{1}{\sqrt{T}}$. The ratio of these two speeds

is $T \frac{d\lambda}{dt}$, that is

$$25 \frac{\sqrt{T} \frac{d\lambda}{dt}}{\frac{1}{\sqrt{T}}} = T \frac{d\lambda}{dt}$$

Instead of using the square root of T in each case any exponent of T could be used as a multiplier for one of the quantities provided that the exponent of T used for the other were made one minus the first exponent. Thus if δ is the exponent then the formula 35 can be written:

$$40 \frac{T^\delta \frac{d\lambda}{dt}}{\frac{1}{T^{1-\delta}}} = T \frac{d\lambda}{dt}$$

It is necessary to read $\sin \mu$ mechanically and transmit it to further mechanism. This is accomplished by the contact roller 197 carried by the pivoted frame 171 and which is adapted to contact with either of the insulated contacts 198 and 199 to complete a circuit through a reversible motor 201 so that the latter is operated in accordance with $T \frac{d\lambda}{dt}$.

50 The motor 201 is connected to the shaft 202 and the latter is geared to the shaft 203, hereinafter referred to, and to the screw follow-up shaft 204 by means of spiral gearing 205. Assuming the contact roller 197 to engage with either of the contacts 198 or 199, the motor 201 is actuated in one direction or the other; and, just as soon as the motor starts, the shaft 204 is actuated in such a direction as to cause the member 206 carrying the contacts 198 and 199 to be traversed to follow the motion of the frame 171, this traversing motion continuing until the frame 171 reaches an equilibrium position when the insulated section 207, between the contacts 198 and 199 comes be-

neath the contact roller 197, whereupon the motor 201 comes to a stop.

The comparators, at 132 and at 133, operate in a manner similar to the comparator, at 131, and the swinging of the frames 171' and 171'' are utilized to control servo-motors 208 and 209 so that the latter move proportionally to the quantities $T \frac{d\alpha}{dt}$ and $T \frac{d\rho}{dt}$, respectively. The servo-motor 208 is connected to a shaft 70 210 which drives the chain 211. In like manner, the motor 209 is connected to a shaft 212 for driving the chain 213.

The shaft 203 and the chains 211 and 213 are driven respectively proportionally to $T \frac{d\lambda}{dt}$, 75 $T \frac{d\alpha}{dt}$, and $T \frac{d\rho}{dt}$ go to the prediction mechanism to operate parts therein as hereinafter described. 80

Taking up now the range and position apparatus, this receives the angle ρ from the telemotor 137 connected to the near station, at 10, and the angle ρ_1 from the telemotor 214 connected to the far station, at 11. The object of the range and position apparatus is to make four determinations from these angles and these determinations are 90

(1) the angle λ which is transmitted by the shaft 134 to the comparator, at 131,

(2) the logarithm of the present range, $\log_{10} R_0$ which is transmitted to the prediction mechanism,

(3) the trigonometric expression or quantity $(\cot \rho + \cot \rho_1)$ which goes to the prediction mechanism; and, 100

(4) the trigonometric expression or quantity $\log_{10} (\cot \lambda - \cot \rho_1)$ which goes to the prediction mechanism.

Referring to the determination of λ , (see Fig. 12) the shaft 215, to which is keyed the bevel gear 216 of the subtraction differential, at 217, transmits ρ_1 to the latter. The angle ρ comes from the shaft 138 (Fig. 10b), being transmitted from the gear 218 keyed to that shaft and by such gear to the gear 219 keyed to the shaft 220. The gear 219 has connected thereto the bevel gear 222. The bevel gears 216 and 222 mesh with the bevel pinions 223 pivoted to the carrier 224, which has a bevel gear portion 225 thereon meshing with the bevel gear 226 on the shaft 134 going to the comparator, at 131. It will be obvious that the effect of the differential is to subtract ρ from ρ_1 ($\rho_1 - \rho$) to obtain the angle λ . 110

Taking up next the determination of the logarithm of the present range $\log_{10} R_0$, this is proportional to $\log_{10} \sin \rho_1 - \log_{10} \sin \lambda = \log_{10} \frac{\sin \rho_1}{\sin \lambda}$. This follows from the relation (Fig. 2) $\frac{R_0}{B} = \frac{\sin \rho_1}{\sin \lambda}$ and remembering that the base line B is constant. Corrections for changes in the base line are here- 125

130

inafter referred to. To find $\log_{10} \sin \lambda$, λ is transmitted from a gear 227 carried by the spider 224 and which meshes with a gear 228 loose on the shaft 229. The gear 228 is connected to scroll wheel 231 which drives, through tapes 232, the scroll wheel 233, the latter being loose on the shaft 234. The function of these scroll wheels is to change λ into $\log_{10} \sin \lambda$ and an outline of wheels suitable for this purpose is indicated in detail in Fig. 13.

Finding next $\log_{10} \sin \rho_1$, ρ_1 shaft 215 has keyed thereto a gear 235, which meshes with a gear 236 keyed to the shaft 229 which is thus also a ρ_1 shaft. Connected to the shaft 229 and to the gear 236 there is a tape wheel 237 connected by suitable tape devices to a wheel 239 keyed to the shaft 234, so that the latter wheel and the latter shaft operate as $\log_{10} \sin \rho_1$. These tape wheels are shown diagrammatically in greater detail in Fig. 14. The tape wheel 237 here shown is a double tape wheel, since ρ_1 passes through 90° and the function $\log_{10} \sin \rho_1$ must reverse. The action of such a tape wheel can easily be understood by first considering only the central heart shaped portion of cam 237 shown in dotted lines. The tape 238 is attached at point 234' at the reentrant angle of the heart and can be wrapped on either face. If the tape is wrapped on one of the faces and the cam then revolved in such a direction as to unwrap it, the tape will slacken, allowing wheel 239 to revolve in an anti-clockwise direction until shaft 229, point 234' and the point of tangency of the tape with wheel 239 lie in a straight line, after which the tape will be pulled so as to cause wheel 239 to revolve in a clockwise direction, thus causing reversal of 239 while 229 revolves in a single direction. As the heart-shaped interior portion of 237 allows only a very limited rotation of 229 in either direction, two cheek members are fastened one on each side of the central member. These are shown by the solid lines of 237, (Fig. 14 and Fig. 12). A tape is used which for a length equal to the length of the cam face from point 234' to the apex of the heart, is narrow enough to slip between the cheek members and then broadens so as to ride on the cheek members, which are so shaped as to continue the curve of the central portion, the whole curve being so designed as to transform ρ_1 at 229 into $\log_{10} \sin \rho_1$ at 234. The shaft 234 transmits $\log_{10} \sin \rho_1$ to the sun gear 242 while the scroll wheel 233 transmits $\log_{10} \sin \lambda$ to the internal orbit gear 243 of the subtraction differential, at 244. This differential has planet pinions 245 meshing with the gears 242 and 243 and carried by the gear 246. The latter gear moves in accordance with the difference of the sun and orbit gears, that is, as $\log_{10} \sin \rho_1 - \log_{10} \sin \lambda$, which is equal to $\log_{10} R_0$. The gear 246 transmits $\log_{10} R_0$ to the gear

247, keyed to the shaft 248, which goes to the prediction mechanism.

To determine $\log_{10} (\cot \lambda - \cot \rho_1)$, this expression is transformed into $\log_{10} \sin \rho - \log_{10} \sin \lambda - \log_{10} \sin \rho_1$. The shaft 234, 70 representing $\log_{10} \sin \rho_1$, has connected thereto the bevel gear 250 of the addition differential, at 251. The spider 252 of this differential, carrying the pinions 253 meshing with the bevel gear 250, is rigid with the scroll wheel 233 and, therefore, represents $\log_{10} \sin \lambda$. The bevel gear 254 of this differential, therefore, represents $\log_{10} \sin \lambda + \log_{10} \sin \rho_1$ and this sum is to be subtracted from $\log_{10} \sin \rho$. The gear 254 is fastened to the shaft 255 to the other end of which is keyed the bevel gear 256 of the subtraction differential at 257. The function $\log_{10} \sin \rho$ is next determined and transmitted to the other bevel gear 258 of the differential at 257, so that the planet pinions 259, their carrier 261, and the shaft 262 connected to the latter represent $\log_{10} \sin \rho - \log_{10} \sin \rho_1 - \log_{10} \sin \lambda$. $\log_{10} \sin \rho$ is determined by transmitting ρ from the shaft 220 and the gear 263 carried thereby through idler 263' to gear 264, which is keyed to shaft 265 and is connected to the tape wheel 266, which is connected by a tape 267 to the tape wheel 268 connected to the bevel gear 258. The wheels 266 and 268 are similar to 95 the wheels 237 and 239. The shaft 262, therefore, represents $\log_{10} (\cot \lambda - \cot \rho_1)$ and it goes to the prediction mechanism.

The next quantity to be determined by the range and position apparatus and transmitted to the prediction mechanism is $\cot \rho + \cot \rho_1$. To determine $\cot \rho$, ρ shaft 265 has keyed thereto the gear 270, which meshes with the gear 271 loosely mounted on the shaft 220 and carrying a scroll wheel 272 100 which cooperates with the scroll wheel 273 loosely mounted on the shaft 255 to transform ρ into $\cot \rho$. In like manner ρ_1 is transmitted from the gear 274 to gear 275 loosely mounted on shaft 220 and connected to scroll wheel 276 which cooperates with the scroll wheel 277 loosely mounted on the shaft 255 to transform ρ_1 into $\cot \rho_1$. Co-tangent scroll wheels suitable for this purpose are shown in Fig. 15 (Sheet 10). The driven scroll wheels 273 and 277 loosely mounted on the shaft 255 are connected, respectively, to bevel gears 278 and 279 of the addition differential, at 280, whose pinions 282, meshing with the bevel gears 278 and 279 and carried by the carrier 283, represent $\cot \rho + \cot \rho_1$. The latter quantity is transmitted from a gear member 284, disposed circumferentially of the differential, at 280, to a gear 285 connected to the shaft 286 going to the prediction mechanism.

Up to this point, I have described in detail apparatus for determining and transmitting the quantities $T \frac{d\lambda}{dt}$, $T \frac{d\alpha}{dt}$, $T \frac{d\rho}{dt}$, $\log_{10} R_0$, $\log_{10}$ 130

$(\cot \lambda - \cot \rho_1)$ and $(\cot \rho + \cot \rho_1)$, to the prediction mechanism, which utilizes these quantities mechanically to determine

- (a) the "future" range $\log_{10} R'$ corrected for parallax, (R_g) ,
 (b) the "future" secondary angle ρ' ,
 (c) the difference between the present and the future primary angles ϕ ,
 (d) the parallax correction θ for "future" secondary angle ρ' .

The first of these quantities, $\log_{10} R_g$, is transmitted to the ballistic mechanism, whereas the last three are transmitted to the transformer of coordinates device.

15 The formulas used in the prediction mechanism are derived as follows:

Given the instantaneous values of the three coordinates of the position of an aeroplane and the rate at which each of these is changing at that instant (any system of coordinates whatever being employed), it is possible to calculate the coordinates of the position the aeroplane will occupy after any given time interval, on the assumption that 20 its velocity is uniform and its course is a straight line. The formulas for performing these calculations are here developed for ordinary spherical coordinates and certain modifications of these.

30 In Fig. 2^b the line A B represents the path of an aeroplane during the "prediction interval", T. At O is an observation station consisting of a telescope mounted so that the primary movement of its supporting frame 35 is about an axis O F, which we will consider horizontal, and its secondary movement about an axis perpendicular to the first. Fig. 2^a represents a plane through O, perpendicular to O F, with the path of the aeroplane, A' B', projected on it. L is the projection of R, the true range to the point A (the position of the target at the instant of observation) and is the angle between the horizontal plane and the plane α through the line O F and the point A', that is the primary angle measured by the observing telescope. L' and α' are the corresponding quantities for the point B', the future position of the target. The correction which must be added to α to obtain α' is $\alpha' - \alpha = \phi$.

Assume for the moment that the coordinates used are L, α , and ρ , (the latter being the angle F O A, Fig. 2^b). The point D represents a point separated by an infinitesimal distance from A', and which the projection of the target will reach in time dt . Then in the right triangle A' D C, $A'C = dL$ and $CD = Ld\alpha$. As the point D moves uniformly along A' B', its projection on the fixed line O A' will move uniformly also. After time T, D will reach B' and C will reach E.

$OE = OA' - EA' = OA' + A'E = L + T \frac{dL}{dt} \left(\frac{dL}{dt} \right)$
 in the figure is negative since L is decreasing)

$$\tan \phi = \frac{TL \frac{d\alpha}{dt}}{L + T \frac{dL}{dt}} = \frac{T \frac{d\alpha}{dt}}{1 + \frac{T dL}{L dt}} \quad (1) \quad 70$$

$$L' = \frac{L + T \frac{dL}{dt}}{\cos \phi} = L \frac{1 + \frac{T dL}{L dt}}{\cos \phi} \quad (2) \quad 75$$

In Fig. 2^b angle $FOA = \rho$, the secondary angle measured by the observing telescope to the point A, and angle $FOB = \rho'$, the secondary angle to the point B. The correction which must be added to ρ to obtain ρ' is $\rho' - \rho = \psi$. Figure 2^c is a flat view of the plane F O A, G being the projection of the point B. The point M represents a point separated by an infinitesimal distance from A and which the projection of the target will reach in time dt . Then in the right triangle A M N, $AN = dR$ and $NM = R d\rho$. As the point M moves uniformly along A G its projection on the fixed line O A will move uniformly also. After time T, M will reach G and N will reach J.

$$Then AJ = \frac{T}{dt} dR = T \frac{dR}{dt} \quad and \quad 95$$

$$JG = \frac{T}{dt} R d\rho = T R \frac{d\rho}{dt}.$$

The angle G O A will not represent ψ since ρ' and ρ are measured in different planes (although it was justifiable to state that $MOA = d\rho$ since in this case the angle between the planes was infinitesimal and the projected angle would therefore differ from $d\rho$ only by an infinitesimal of higher order).

From G draw G F $\perp$ to O F, thus determining the point F. Draw F B (Fig. 2^b). Then O F B is a right triangle and: $BF = R' \sin \rho'$ and $OF = R' \cos \rho'$. From F draw F P $\perp$ to O A. Then $FP = R' \cos \rho' \sin \rho$. The angle $GFB = \phi$ = angle between planes F O A and F O B. The angle B G F = a right angle, G being a projection of B on plane F O A. Then $GF = BF \cos \phi = R' \sin \rho' \cos \phi$. From G draw G K $\perp$ to F P. Then $GFK = \rho$ (see Fig. 2^c).

$$FK = FG \cos \rho = R' \sin \rho' \cos \phi \cos \rho. \quad 110$$

$$KP = FP - FK = R' \cos \rho' \sin \rho - R' \sin \rho' \cos \phi \cos \rho. \quad 120$$

$$But KP = -JG = -RT \frac{d\rho}{dt}$$

$$\therefore -RT \frac{d\rho}{dt} = R' \cos \rho' \sin \rho - R' \sin \rho' \cos \rho \cos \phi. \quad 125$$

$$65 Then A'E = \frac{T}{dt} dL = T \frac{dL}{dt} \quad and \quad EB' = \frac{T}{dt} L d\alpha = TL \frac{d\alpha}{dt}$$

$$-\cos \rho' \sin \rho = T \frac{d\rho}{dt} \frac{R}{R'} - \sin \rho' \cos \rho \cos \phi.$$

$$\cos \phi = 1 - \text{vers } \phi.$$

$$5 -\cos \rho' \sin \rho = T \frac{d\rho}{dt} \frac{R}{R'} - \sin \rho' \cos \rho + \sin \rho$$

$$\cos \rho \text{ vers } \phi.$$

$$10 \sin (\rho' - \rho) = \sin \psi = T \frac{d\rho}{dt} \frac{R}{R'} + \sin \rho' \cos \rho$$

$$\text{vers } \phi. \quad (3)$$

But since $L = R \sin \rho$ and $L' = R' \sin \rho'$.

$$15 \sin \psi = T \frac{d\rho}{dt} \frac{L \sin \rho'}{L' \sin \rho} + \sin \rho' \cos \rho \text{ vers } \phi \quad (4)$$

$$\log R' = \log R + \log \left(1 + T \frac{d \log R}{dt} + \cot \rho T \frac{d\rho}{dt} \right) - \log \cos \phi + \log \sin \rho - \log \sin \rho' \quad (11)$$

$$20 \sin \psi = T \frac{d\rho}{dt} \text{ antilog} (\log R - \log R') + \sin \rho' \cos \rho \text{ vers } \phi \quad (12) \quad 85$$

Formulas (1), (2) and (4) are prediction formulas which use as coordinates the angles α and ρ , as above defined and L , the projection of the true range of the target on a plane perpendicular to the axis of primary rotation of the observing telescope. As absolute directions in space are immaterial, these formulas apply directly to the case where the observing telescope is mounted like an ordinary transit so that α is the azimuth, ρ the complement of the elevation and L the horizontal range.

35 Instead of using L and its rate of change, $\frac{dL}{dt}$, the log of L and the rate of change of this quantity may be substituted.

$$40 \frac{1}{L} \frac{dL}{dt} = \frac{d \log L}{dt}$$

The formulas then become:

$$45 \tan \phi = \frac{T \frac{d\alpha}{dt}}{1 + T \frac{d \log L}{dt}} \quad (5)$$

$$50 \log L' = \log L + \log \left(1 + T \frac{d \log L}{dt} \right) - \log \cos \phi. \quad (6)$$

$$\sin \psi = T \frac{d\rho}{dt} \frac{\sin \rho'}{\sin L} \text{ antilog} (\log L - \log L') + \sin \rho' \cos \rho \text{ vers } \phi. \quad (7)$$

The usual spherical coordinates are α , ρ and R . Formulas using these are derived as follows:

$$L = R \sin \rho \quad L' = R' \sin \rho'$$

$$\frac{dL}{dt} = \sin \rho \frac{dR}{dt} + R \cos \rho \frac{d\rho}{dt}$$

60 Substituting in (1) and (2)

$$65 \tan \phi = \frac{T \frac{d\alpha}{dt}}{1 + \frac{T}{R} \frac{dR}{dt} + \cot \rho T \frac{d\rho}{dt}} \quad (8)$$

$$R' = R \frac{1 + \frac{T}{R} \frac{dR}{dt} + \cot \rho T \frac{d\rho}{dt}}{\cos \phi} \frac{\sin \rho}{\sin \rho'} \quad (9)$$

For $\sin \psi$ use (3) previously derived. 70

Since $\frac{d \log R}{dt} = \frac{1}{R} \frac{dR}{dt}$, the corresponding formulas using $\log R$ instead of R are: 75

$$\tan \phi = \frac{T \frac{d\alpha}{dt}}{1 + T \frac{d \log R}{dt} + \cot \rho T \frac{d\rho}{dt}} \quad (10)$$

80

$$\log R' = \log R + \log \left(1 + T \frac{d \log R}{dt} + \cot \rho T \frac{d\rho}{dt} \right) - \log \cos \phi + \log \sin \rho - \log \sin \rho' \quad (11)$$

In the above discussion only a single observation telescope was mentioned. The quantities L , $\log L$, R and $\log R$ may be found either by a range finder or by means of triangulation from two separate stations, the formulas applying equally to either case. Modified formulas will now be developed, however, which apply only to the case of two stations, at the ends of a known base line. In addition to the telescope at O in Fig. 2^a there will now be a second telescope mounted in exactly the same way at some point along the line $O F$ at known distance from O , and the axes of primary movement of the two telescopes will each be coincident with this line. 100

In Fig. 2^a the point O is called the "near station" and the second telescope at the distance B the "far station". The secondary angles measured by these telescopes are designated ρ and ρ_1 .

Then: $R = B \frac{\sin \rho_1}{\sin \lambda}$, where $\lambda = \rho_1 - \rho$, that is λ is the apex angle of the triangle formed by the base line and the two lines of sight. 110

The coordinates of target position now employed will be α and ρ , as heretofore and λ . 120

$$\log R = \log B + \log \sin (\rho + \lambda) - \log \sin \lambda$$

$$\frac{d \log R}{dt} = \cot (\rho + \lambda) \left(\frac{d\rho}{dt} + \frac{d\lambda}{dt} \right) - \cot \lambda \frac{d\lambda}{dt}$$

$$= \cot \rho_1 \frac{d\rho}{dt} + \cot \rho_1 \frac{d\lambda}{dt} - \cot \lambda \frac{d\lambda}{dt}$$

$$= \cot \rho_1 \frac{d\rho}{dt} - (\cot \lambda - \cot \rho_1) \frac{d\lambda}{dt}$$

125

130

Substituting this in (10) and (11)

function wheel 290 which drives function sec-

$$5 \quad \tan \phi = \frac{T \frac{d\alpha}{dt}}{1 + T \frac{d\rho}{dt} (\cot \rho + \cot \rho_1) - T \frac{d\lambda}{dt} (\cot \lambda - \cot \rho_1)} \quad (13)$$

$$10 \quad R' = R \frac{1 + T \frac{d\rho}{dt} (\cot \rho + \cot \rho_1) - T \frac{d\lambda}{dt} (\cot \lambda - \cot \rho_1)}{\cos \phi \cos \psi (1 + \cot \rho \tan \psi)} \quad (14)$$

The denominator in Equation (14) results from the transformation:

$$15 \quad \text{antilog} (\log \sin \rho - \log \sin \rho') = \frac{\sin \rho}{\sin \rho'} =$$

$$\frac{\sin \rho}{\sin \rho \cos \psi + \cos \rho \sin \psi} = \frac{1}{\cos \psi + \cot \rho \sin \psi} =$$

$$20 \quad \frac{1}{\cos \psi (1 + \cot \rho \tan \psi)}$$

The formula for the secondary angle is: (from (12))

$$25 \quad \sin \psi = T \frac{d\rho}{dt} \frac{R}{R'} + \sin \rho' \cos \rho \text{ vers } \phi$$

or approximately:

$$30 \quad \psi = T \frac{d\rho}{dt} \frac{R}{R'} + \sin \rho' \cos \rho \text{ vers } \phi \quad (15)$$

The Equations (13), (14) and (15) are the ones used in the device, Equation (14) best expressed in logarithmic form.

By letting $1 + T \frac{d\rho}{dt} (\cot \rho + \cot \rho_1) - T \frac{d\lambda}{dt} (\cot \lambda - \cot \rho_1) = K$, the operations of solving Equations (1) and (2) may be simplified in which case

$$(4) \quad \phi = \tan^{-1} \frac{T d\alpha}{K t d}$$

$$45 \quad (5) \quad \log_{10} R' = \log_{10} R_0 + \log_{10} K - \log_{10} \cos \phi - \log_{10} \cos \psi - \log_{10} (1 + \cot \rho \tan \psi).$$

From the definitions given, the above equations follow from a series of mathematical steps, the proof of which is unnecessary to a disclosure of the present invention.

In describing the prediction mechanism, it will be taken up first with respect to solving for ϕ , and then with respect to $\log_{10} R'$ followed with respect to ψ .

In solving for ϕ , the mechanism for finding K will be considered first, K being equal

$$1 + T \frac{d\rho}{dt} (\cot \rho + \cot \rho_1) - T \frac{d\lambda}{dt} (\cot \lambda - \cot \rho_1),$$

two multiplication and one subtraction processes are necessary. A multiplying apparatus M_1 is used for finding $T \frac{d\lambda}{dt} (\cot \lambda - \cot \rho_1)$;

and, referring to Figs. 16, 17 and 18 shaft 262

65 representing $\log_{10} (\cot \lambda - \cot \rho_1)$ carries

tor 291, which is pivoted at 292. The sector 291 has an integral crank arm 293, which is pivoted at 294 centrally of the link 295 having rollers 296 and 297 fitting slots 298 and 299 arranged, respectively, in the vertical stationary guide member 301 and in the multiplying arm 302 pivoted at 303 to a block 304. The lengths 296 to 294, 294 to 297 and 294 to 292 are all equal. From this structure, it will be apparent that the axis of roller 297 will move in a straight line $a-a$, its position along this line being determined by rotation of the function wheels 290 and 291, these function wheels converting $\log_{10} (\cot \lambda - \cot \rho_1)$ represented by the angular position of 290 into $(\cot \lambda - \cot \rho_1)$ represented by ratio of the distance PD to the distance PC. A guide member 305 is arranged parallel to the screw 311 and at right angles to the line $a-a$, and a carriage 306 is movable therealong, the carriage 306 having a roller 307 which fits in the slot 299 of the arm 302. With this apparatus, the roller 297 so moves that its axis P is distant from points of intersection D and C of the line $a-a$ and the verticals from the axes of the roller 307 and of the axis 303 such that $\frac{PD}{PC}$ represents $(\cot \lambda - \cot \rho_1)$.

The next operation is to multiply $(\cot \lambda - \cot \rho_1)$ by $T \frac{d\lambda}{dt}$. Shaft 203, representing $T \frac{d\lambda}{dt}$ has a bevel gear 308 meshing with the bevel gear 309 at the upper end of the screw shaft 311, which is threaded to the block 304 slidable on the guide rod 312. CE is therefore, proportional to $T \frac{d\lambda}{dt}$; and, since $\frac{PD}{PC}$ ($= \frac{FD}{CE}$) is thus made proportional to $(\cot \lambda - \cot \rho_1)$, it follows that FD is proportional to $T \frac{d\lambda}{dt} (\cot \lambda - \cot \rho_1)$. Therefore, the distance FD of the carriage 306 from its zero position will represent this product.

The zero positions for points E and F must lie on the line $a-a$ since it is only when these points lie on this line that the pivot P can move from side to side without causing displacement of F.

The carriage 306 is connected by a tape 130

passing over the sheaves 314 to a tape wheel 315 carried by a shaft 316 (Fig. 16).

The product $T \frac{d\rho}{dt} (\cot \rho + \cot \rho_1)$ is obtained by the multiplier, at M2. Referring to Figs. 19 and 20, $T \frac{d\rho}{dt}$ is supplied by the shaft 317 driven by the sprocket chain 213 coming from the comparator 133, the shaft 317 having connected thereto a bevel gear 318 meshing with the bevel gear 319 carried by the shaft 320 mounted in a bearing 321 carried by the fixed support 322. An arm 323 is pivoted intermediately of its length with respect to the support by a ball bearing 324. The shaft 320 is connected by universal joints 325 and 326 and an intermediate slip joint 327 to the shaft 328 carried by bearings 329 on the arm 323, the universal joints and slip joint permitting of motion being transmitted from the shaft 320 to the shaft 328 even though the arm is turned about the axis o of the bearing 324.

The shaft 328 has fixed to its outer end a bevel gear 331 meshing with a bevel gear 332 mounted on one end of a screw 333, which is disposed within the slot 334 in the arm 323 and is rotatably mounted in bearings 335 and 336 so that the axis of the screw intersects the axis of the supporting bearing 324.

A block 337 is threaded to the screw 333 and it is provided with lateral tongues 338 fitting in guide grooves 339 in the opposed walls of the slot 334. The block 337 carries a roller 341 whose distance from the axis o of the supporting bearing 324 is dependent solely upon the rotational position of the shaft 320 and it is not affected by the swing of the arm 323; and it is so arranged that, when shaft 320 represents a zero value of $T \frac{d\rho}{dt}$, the roller 341 is at the axis o , negative values being to one side and positive values to the other side of that axis.

The swing of the arm 323 is controlled by a scroll wheel 342 carried thereby and driven by a scroll wheel 343 on the shaft 286, coming from the range and position apparatus and representing $\cot \rho + \cot \rho_1$, the scroll wheels being so cut that $\sin \varpi$ is proportional to the angular rotation of shaft 286, ϖ being zero and the arm 323 horizontal when $(\cot \rho + \cot \rho_1)$ is zero.

From the arrangement so far described, it will be obvious that the normal distance of the axis S of the roller 341 from the horizontal through the axis of supporting bearing 324, distance PS, is equal to OS $\sin \varpi$, that is, it will be proportional to $T \frac{d\rho}{dt} (\cot \rho + \cot \rho_1)$.

Vertical motion of the roller 341, that is $T \frac{d\rho}{dt} (\cot \rho + \cot \rho_1)$, is transmitted to the horizontally disposed parallel motion bar 344,

the bar having a slot 345 in which the roller 341 fits. The ends of the bar are connected to a tape 346 which is in effect continuous. The tape passes over upper sheaves forming vertical strands 346^a, 346^b, 346^c and 346^d. The inside strands pass down and under the inside sheaves 349 and 350 and the outside strands pass down and under the outer sheaves 352 and 353. One end of the bar 344 is connected to an inner strand while the other end of the bar is connected to an outer strand at the other side. Motion of the tape 346 is transmitted to the wheel 354 loose on the shaft 316.

Referring to Figs. 10^a and 16, it will be seen that shaft 316 is driven by the multiplier M1 proportionally to $T \frac{d\lambda}{dt} (\cot \lambda - \cot \rho_1)$ while the wheel 354 loosely mounted on that shaft is driven by the multiplier M2 proportionally to $T \frac{d\rho}{dt} (\cot \rho + \cot \rho_1)$. The shaft 316 is connected to the sun gear 355 of the subtraction differential, at 356, while the planet pinions 357 of that differential are carried by the tape wheel 354. The orbit gear 358 will, therefore, be driven as $T \frac{d\rho}{dt} (\cot \rho + \rho_1) - T \frac{d\lambda}{dt} (\cot \lambda - \cot \rho_1)$ and the constant "1" is supplied by the angular setting on the shaft 359 so that the latter represents K, which is equal to $1 + T \frac{d\rho}{dt} (\cot \rho + \cot \rho_1) - T \frac{d\lambda}{dt} (\cot \lambda - \cot \rho_1)$.

Having found the factor K mechanically, the next step is to utilize the motion or position of K shaft 359 together with the factor $T \frac{d\alpha}{dt}$ in determining a function of ϕ , since

$$\phi = \tan^{-1} T \frac{d\alpha}{dt} / K$$

This is accomplished by the multiplier M3 and the succeeding differential mechanism. Referring first to the multiplier M3 (see Figs. 16 and 21), chain 211 coming from comparator 132 operates shaft 361 connected to bevel gears 362 meshing with gear 363 carried by shaft 364, the latter being mounted in bearings on the stationary supporting structure and having universal and slip joint connections to a shaft member carried by the arm 365 movable about the axis of the bearing indicated by the circle 366. These parts are similar to corresponding parts of multiplier M2. Motion is transmitted from the shaft 364 through the bevel gear 366 to the bevel gear 367 on one end of the screw shaft 368, which is mounted in bearings carried by the arm 365 and which is arranged in the slot 369 so that its axis intersects the axis o of the supporting bearing. The screw 368 traverses a block 371 in the slot 369 so that the distance of the axis of its roller 376 from the axis o is proportional to $T \frac{d\alpha}{dt}$.

Since variations in K may be small or

slightly above or below unity, I prefer to change K into a function $\frac{1-K}{K}$ before utilizing it in the multiplier so that a small change in K may be represented by a much greater change in $\frac{1-K}{K}$. Shaft 359, representing K , has a function wheel 372 which cooperates with the function wheel 373 on the arm 365 to swing the latter as $\frac{1-K}{K}$. Thus the sine of the angle of the arm 365 from the horizontal will be proportional to $\frac{1-K}{K}$. Under these conditions, the parallel motion bar 374, having a slot 375 engaging the roller 376 on the block 371, will move as the product of $\frac{1-K}{K}$ and $T \frac{d\alpha}{dt}$ or $\left[T \frac{d\alpha}{dt/K} - T \frac{d\alpha}{dt} \right]$. This motion is conveyed by a tape 377 to the tape wheel 378 loosely mounted on the shaft 361. In order that the second term, $T \frac{d\alpha}{dt}$, may be removed

from this quantity, $T \frac{d\alpha}{dt}$ is added in the differential, at 379. The orbit gear 381 of this differential is integral with the tape wheel 378 and the sun gear 382 is connected to $T \frac{d\alpha}{dt}$ shaft 361. The result is that the planet pinions 383 and the carrier 384 are driven as $T \frac{d\alpha}{dt/K}$ which is equal to $\tan \phi$. This spider is connected to $\tan \phi$ shaft 285 which is used with other mechanism wherever ϕ or a function of ϕ is required as hereinafter set forth.

The next operation is to find $\log_{10} R'$ (the $\log_{10}$ of the "future" range) which is equal to $\log_{10} R_0 + \log_{10} K - \log_{10} \cos \phi - \log_{10} \cos \psi - \log_{10} (1 + \cot \rho \tan \psi)$. Assuming that ψ is known, and it is determined by apparatus hereinafter described, it is apparent that $\log_{10} R'$ may be determined by processes of addition and subtraction in differentials and a process of multiplication in a multiplier.

Taking up first the term $\log_{10} K$, K shaft 359 (Fig. 16) has a scroll wheel 386 keyed thereto which cooperates with a scroll wheel 387 constituting a spider or carrier of the differential, at 388. The function of these scroll wheels is to change K into $\log_{10} K$. In Fig. 22 (Sheet 11) I show diagrammatically a pair of wheels suitable for this purpose.

The term $\log_{10} \cos \phi$ is next determined and subtracted from $\log_{10} K$ in the differential at 388. Referring to Figs. 16 and 23, $\tan \phi$ shaft has a cam 390 against which bears the follower roller 391 pivoted at the hinge axis of ends of the links 392 and 393, the outer end of the lower link 392 being pivoted at 394 and the outer end of the link 393 being pivotally connected to a crank 394' on the bevel

gear 395 of the differential, at 388. The follower 391 is maintained in contact with the cam 390 by a spring 396. The cam 390 has such a contour that motion of shaft 385 is transformed into motion of the bevel gear 395 proportional to $\log \cos \phi$.
70

The bevel gear 395 of the differential, at 388, meshes with pinions 397 carried by the scroll wheel 387, representing $\log_{10} K$; and the pinions 397 mesh with the other bevel gear 398 of the differential so that the movement of the latter gear represents $\log_{10} K - \log_{10} \cos \phi$.
75

The next term to be determined is $\cot \rho \tan \psi$ involving a process of multiplication. To this end, ψ shaft 399 has a scroll wheel 401 thereon which drives scroll wheel 402 on the arm 403 of the multiplier M4 (see Fig. 24, Sheet 15) so that the arm moves about its axis so that the sine of the angle it forms with the horizontal is proportional to $\tan \psi$. The shaft 404, representing ρ , is connected by gears 405 and 406 to ρ shaft 138, aforesaid. The shaft 404 drives the screw 407 mounted in the arm 403 proportionately to ρ through the gears 408 and 409. As shown in Figs. 24 and 25, the screw 407 is of variable pitch, that is, it is a function screw, so that the distance the block 411 is traversed by the screw from the axis of arm 403 is proportional to $\cot \rho$. With this arrangement of screw and arm, the vertical displacement of the roller 412 will be proportional to $\cot \rho \tan \psi$. The roller engages the slot 413 in the parallel motion bar 414, the ends of the latter being connected to the tape 415 which actuates the tape wheel 416 connected by a sleeve 417, rotatably mounted on the shaft 418, to a function wheel 419 engaging the function wheel 420. The function wheel 419 is set angularly with respect to the tape 416 so that it represents $(1 + \cot \rho \tan \psi)$ and the function wheels 419 and 420 serve to change this into $\log_{10} (1 + \cot \rho \tan \psi)$ for the latter function wheel.
90

The wheel 420 constitutes a carrier for the planet pinions 421 of the differential at 422.
95

Shaft 399 representing ψ has keyed to it a cam 423, which operates the follower roller 424 (see Fig. 26) to swing the link 425, supported at one end by a link 426 having a fixed pivot 427, the other end of the link 425 being pivotally connected to the crank 428 fixed to the shaft 429. The linkage is constrained by the spring 431 to maintain contact of the follower 424 with the cam 423. The cam is shaped to change ψ into an angular movement of the shaft 429 proportional to $\log_{10} \cos \psi$.
105

The shaft 429 is fixed to the sun gear 431 of the differential at 422 moving the latter proportionally to $\log_{10} \cos \psi$; and since the planet pinions of this differential are moved proportionally to $\log_{10} (1 + \cot \rho \tan \psi)$, the orbit gear 432 thereof and the shaft 433 to which the latter gear is connected will be 110
120
125
130

moved proportionally to the sum, namely $\log_{10} \cos \psi + \log_{10} (1 + \cot \rho \tan \psi)$.

The shaft 433 representing $\log_{10} \cos \psi + \log_{10} (1 + \cot \rho \tan \psi)$ drives the pinions 434 of the subtraction differential, at 435 the bevel gear 436 of the latter being connected to the bevel gear 398 so that it moves proportionally to $\log_{10} K - \log_{10} \cos \phi$. Therefore, the other bevel gear 437 of this differential 5 will move proportionally to $\log_{10} K - \log_{10} \cos \phi - \log_{10} \cos \psi - \log_{10} (1 + \cot \rho \tan \psi)$ which is equal to $\log_{10} R' - \log_{10} R_0$, or $\log_{10} \frac{R'}{R_0}$. The gear 437 carries a spur gear 438 10 meshing with the spur gear 439 keyed to shaft 15 418 so that the latter moves as $\log_{10} \frac{R'}{R_0}$.

To find $\log_{10} R'$, it is merely necessary to 20 add $\log_{10} R_0$, but it is more convenient to first add the correction to range for parallax (the 25 parallax apparatus is later described) which is represented by the tape 441, which actuates the sun gear 442 of the addition differential, at 443, the orbit gear 444 of which is connected to the shaft 418 representing $\log_{10} \frac{R'}{R_0}$, 30 so that the planet pinions 445, their carrier 446, and the connected gear 447 move proportionally to $\log_{10} \frac{R'}{R_0} + \text{parallax correction to } R_0$,

R₀, the latter quantity being transmitted to the gear 448 connected to the sun gear 449 of the addition differential at 451, the orbit gear 35 452 of the latter being connected to shaft 248 representing $\log_{10} R_0$ and coming from the range and position apparatus. Hence, it follows that the planet pinions 454 of the differential, at 451, the carrier 455, and the connected shaft 456 will operate as $\log_{10} R' + \text{parallax correction, namely, the "future range" corrected for parallax, or } \log_{10} Rg$.

The shaft 456 is connected to the ballistic apparatus and to the parallax apparatus to 45 transmit thereto $\log_{10} R'$ corrected for parallax. To this end, the shaft 456 is connected to a disk 457 having an adjustable ring 458 therearound (Fig. 27); and the ring is connected by a gear 459 to a gear 565m' of parallax apparatus at 461 and by tapes 462 to the ballistic apparatus.

As shown in Fig. 27, the ring 458 is adjustable with respect to the disk 457, the ring 458 having graduations 463 reading in lengths of the base line. Thus, if the base line, instead of being the 2000 feet selected for a standard, should be a few hundred feet more or less, this can be corrected for by altering the angle between the disk and the ring by an 55 amount equal to the difference between the logarithms of the actual and standard base lines, an operation which may be facilitated by having the scale divisions represent logarithms.

65 So far, the prediction mechanism has been

described with respect to obtaining the tangent of the azimuth angle correction ϕ and $\log_{10} R'$ corrected for parallax, both of which will be referred to later. The only other quantity left for solution in the prediction mechanism is the vertical angle correction ψ .

As already pointed out

$$\psi = \sin^{-1} \left[T \frac{d\rho}{dt} \frac{R_0}{R'} + \sin \rho' \cos \rho \text{ vers } \phi \right].$$

The first step in the solution is to multiply 75 $T \frac{d\rho}{dt}$ by $\frac{R_0}{R'}$. This is done by the multiplier

M5, see Fig. 28. The shaft 418 representing

$\log_{10} \frac{R'}{R_0}$ has fixed thereto the scroll wheel 465 80

engaging the scroll wheel 466 and moving the arm 467 about its pivot such that the sine of the angle from a horizontal position is proportional to $\frac{1 - R'/R_0}{R'/R_0}$. Shaft 317, representing 85

$T \frac{d\rho}{dt}$, is connected by gears 468 and

469 to shaft 470, the latter actuating the screw 471 carried by the arm 467 so that the block 472 is moved in the slot 473 of the arm such that the distance of the roller 474 on the block from the axis of the arm is proportional to $T \frac{d\rho}{dt}$. Hence, the vertical displacement 90

of the parallel motion bar 475 by the roller 474 will be proportional to

$$\left(T \frac{d\rho}{dt} \frac{R_0}{R'} - T \frac{d\rho}{dt} \right).$$

This quantity is transmitted by the tape 476 100 to the tape wheel 477, loose on the shaft 317, to the addition differential, at 478 where the last term, $T \frac{d\rho}{dt}$, is removed.

The tape wheel 477 carries the orbit gear 479 of the differential, at 478, representing $(T \frac{d\rho}{dt} \frac{R_0}{R'} - T \frac{d\rho}{dt})$ while the sun gear 480 is connected to shaft 317 representing $T \frac{d\rho}{dt}$. The 110 planet pinions 481, the carrier 482, and the shaft 483, therefore, move as $T \frac{d\rho}{dt} \frac{R_0}{R'}$.

The next quantity to be determined is $\sin \rho' \cos \rho$. ρ' , to be determined later, is fed back by sprocket chain 486 from ρ' shaft 485 to shaft 487, which carries a pinion 488 meshing with the sector 489 of an arm 491 of the multiplier M6 so that the angle of arm 491 from the horizontal represents ρ' (see Fig. 29). Shaft 115 492, representing ρ' , is connected, by gears 492 and 493 to shaft 494, the latter shaft being connected, by bevel gearing 495, to shafting mechanism 496 including universal joints and a slip joint and whose other end is geared by gearing 497 to the screw or function shaft 498 carried by the arm. The shaft 498 rotates as ρ , but the variable pitch of its thread or cam groove (see Fig. 30) causes the 120 125 130

block 500 to be traversed from the axis of the arm 491 as $\cos \rho$. From this, it follows that the vertical displacement of the roller 503 from a horizontal through the axis of arm 491 is proportional to $\sin \rho' \cos \rho$.

The next step is to ascertain $\text{vers } \phi$ and multiply it by $\sin \rho' \cos \rho$. Referring to Figs. 16, 31 and 32, and particularly to Fig. 32, tan ϕ shaft 385 has keyed thereto, a function wheel 504 which drives the function wheel 505 freely mounted on the shaft 418 and having integral therewith the bevel gear 506 which meshes with the bevel gear 507 carried by shaft 508 of multiplier M7. The function wheels cooperate with succeeding linkage to transform tan ϕ into vers ϕ .

The parallel motion bar 501 of the multiplier M6 transmits $\sin \rho' \cos \rho$ directly to the multiplier M7. To this end, the bar 501 is provided with a slot 510 (see Fig. 29) which engages a roller 511 (see Fig. 31) carried by the arm 512, pivoted at 513, so that when this arm is swung about its axis, the sine of its angle of displacement from a horizontal is proportional to $\sin \rho' \cos \rho$.

Shaft 508 drives the shaft 514, fitting bearings 515 and 516 carried by the arm 512, through the intermediary of the universal joints 517 and 518 and a slip joint 519 interposed between the latter. The shaft 514 carries a bevel gear 521 disposed between the bearings 515 and 516 and meshing with the bevel gear 522 keyed to shaft 523, the latter being journaled in spaced bearings 524 and 525 carried by the arm 512. A crank arm 526 is keyed to the shaft 523 between the bearings 524 and 525 and it carries a crank pin 527 journaled in bearings 528 arranged midway of the length of the lever 529. The lever 40 has a roller 531 adapted to fit vertical upper or lower guides 532 or 533, whose center line intersects the axis of shaft 523. To the left, or other end of the lever, there is secured an inside roller 534 adapted to fit the horizontal guide 535. If, with the parts arranged as shown in Figs. 31 and 32, the crank arm 526 is turned clockwise, the roller 531 moves upwardly, and if turned counter-clockwise, it moves downwardly. If turned in either direction, the roller 534 moves toward the right in the slot 535 and the roller 531 moves in the vertical center line of the slots 532 and 533; and the slot 535 is made sufficiently long so that the roller 531 enters either the vertical slot 532 or the vertical slot 533 before the roller 534 leaves the horizontal slot 535.

After leaving the horizontal slot 535, the roller 534 continues to move in the center line prolonged of the slot 535 and intersecting the axis of the shaft 523. The roller 534, therefore, is constrained to move in a straight line which is fixed with respect to the arm 512 and which is the center line of the slot 535; and the distance of the roller 534 from the axis of 65 the pivot 513 of the arm 512, owing to the

combined action of the function wheels 504 and 505 and the linkage just described, will be proportional to $\text{vers } \phi$ while the sine of the angle of the swing of the arm is proportional to $\sin \rho' \cos \rho$. Hence, the vertical displacement of the roller 534 will be proportional to $\sin \rho' \cos \rho \text{ vers } \phi$. This quantity is transmitted by a roller 536 arranged outwardly and coaxially with respect to the roller 534 and fitting the horizontal parallel motion bar 537, which is connected by tapes 538 to transmit $\sin \rho' \cos \rho \text{ vers } \phi$ to the tape wheel 540, which is connected to the carrier 541 for the planet pinions 542 of the addition differential, at 543. One bevel gear 544 of this differential is keyed to shaft 483, representing

$T \frac{d\rho}{dt} \frac{R_0}{R'}$. Hence the other bevel gear will rotate as $T \frac{d\rho}{dt} \frac{R_0}{R'} + \sin \rho' \cos \rho \text{ vers } \phi$, which is equal to $\sin \psi$; however, as ψ is always a small angle, it may be taken as proportional to its sine.

The angle ψ is transmitted by the gear 546, carried by the gear 545, to the gear 547 freely mounted on ρ' shaft 485 and connected to gear 548 which meshes with gear 549 to drive ψ shaft 399 aforesaid.

Since the "future" vertical angle ρ' is equal to present ρ plus the vertical angle correction ψ , and since both ρ and ψ are now represented mechanically, ρ' may be determined by adding ρ and ψ in the addition differential at 551. Gear 547, representing ψ , is also connected to the carrier 552 of this differential, the carrier having mounted thereon pinions 553 which mesh at one side with a bevel gear 554 connected to ρ shaft 138. At their other sides, these pinions mesh with a bevel gear 555 which rotates as $\rho + \psi$, or ρ' . The latter bevel gear is connected to ρ' shaft 485 aforesaid.

From the foregoing, it will be seen that the prediction mechanism has determined mechanically the following:

(a) the logarithm of the future range (R') corrected for parallax, that is, $\log_{10} R_g$, and which may be corrected for variations in base line by relative adjustment of the rim 458 and the disk 457, the rim transmitting $\log_{10} R'$ corrected for parallax, or $\log_{10} R_g$, to the ballistic mechanism, hereinafter described and to the parallax device, also hereinafter described;

(b) the vertical angle correction ψ has been determined and added to ρ to obtain the "future" vertical angle ρ' which is transmitted to the transformer of coordinates, hereinafter described;

(c) $\tan \phi$ has been determined and applied to the shaft 385, which (see Fig. 33) has connected thereto the tape wheel 556 operating through the tape 557 to drive the wheel 558 including a spring connection 559 with

respect to the shaft 560. The tape wheel 556 is so shaped that $\tan \phi$ motion thereof is converted into ϕ motion of the tape which is transmitted to the wheel 558, the spring 559 keeping the tape taut. This angle is added to α and transmitted to the transformer of coordinates, as hereinafter described.

Before proceeding with the description of 10 the transformer of coordinates, the parallax apparatus which has already been referred

$$\theta \text{ (in radians)} = \frac{G}{R_g} \sin \rho', \text{ that is:}$$

$$\theta \text{ (in degrees)} = 57.3 \frac{G}{R_g} \sin \rho'. \quad 70$$

Since, in any triangle,

$$c = \sqrt{a^2 + b^2 - 2ab \cos C}$$

$$Rg = \sqrt{(R')^2 + G^2 - 2R'G \cos \rho'}$$

$$Rg = \sqrt{R'^2 \left(1 + \left(\frac{G}{R'}\right)^2 - 2 \frac{G}{R'} \cos \rho'\right)} \quad 75$$

$$\log_{10} R_g = \log_{10} R' + 1/2 \times .4343 \log \left[1 + \left(\frac{G}{R'}\right)^2 - 2 \frac{G}{R'} \cos \rho' \right].$$

15 to in connection with the "future" range will now be described. This apparatus is shown diagrammatically at 461 in Fig. 16 and more in detail in Figs. 34 to 39, inclusive. Figs. 20 34 to 37, inclusive, are diagrammatic to explain the principles, while Figs. 38 and 39 show apparatus suitable for the purpose.

The parallax device is used for the reason that the near station telescope cannot be located in close proximity to the gun; and it serves as a correcting device for finding the corrections to be added to the azimuth and vertical angles of the "future" position of the target as measured from the position of sight 30 to change them into the corresponding angles measured from the gun.

Referring to Fig. 34, the gun, at 12, is set up on the base line between the two telescopes and at a distance G from the near telescope, at 10, R' and R_g are the true ranges 35 from the telescope and from the gun, respectively, while ρ' and ρ_g are the secondary angles (the angles between the base line and the target measured in the plane containing the base line and the target) at the telescope and at the gun, respectively. The primary angle (α), that is, the angle between the plane containing the base line and the target and the horizontal plane, is the same for the telescope and for the gun since both are on the base line.

At this point, it is well to explain that the primary and secondary angles are not the angles used in laying the gun, but that these 50 are changed by the transformer of coordinates device into azimuth and vertical angles for such use. These transformations might be effected before parallax was calculated, but if this were done, corrections would have 55 to be made both to the azimuth and to the vertical angles, whereas with my arrangement only one angle, the secondary angle ρ , requires such correction.

Continuing the explanation of Fig. 34, 60 the correction for the range is $R_g - R'$ while the correction, θ , for the secondary angle is equal to $\rho_g - \rho'$.

65 $\sin \theta = \frac{G \sin \rho'}{R_g} = \frac{G}{R_g} \sin \rho'$, or approximately

80 In the parentheses, the term $\left(\frac{G}{R'}\right)^2$ may be neglected and $\log (1 - x) = -x$ for small values of x .

The last equation then simplifies to— 85

$$\log_{10} R_g = \log_{10} R' - .4343 \frac{G}{R'} \cos \rho'.$$

The correction P , to $\log_{10}$ of range is equal to $P = -.4343 \frac{G}{R'} \cos \rho'$ or since R_g can be 90 substituted for R' without appreciable error, this equation can be written:

$$P = -.4343 \frac{G}{R_g} \cos \rho' \quad (1) \quad 95$$

The correction to the secondary angle is:

$$\theta \text{ (in degrees)} = 57.3 \frac{G}{R_g} \sin \rho' \quad (2)$$

These last two approximate formulae are 100 the only ones used in the device.

Fig. 35 shows diagrammatically the mechanical principles of the device. Here ρ' is applied from the pinion a to the toothed sector b so that the slot c with which the latter is provided makes the angle ρ' with the vertical. In slot c , slides a block holding a pin e engaging in slots f and g of vertical and horizontal parallel bars f' and g' . The block is so set in the slot c , from information received elsewhere, that the distance from the axis of pin e to the axis h of the sector b is proportional to $\frac{G}{R_g}$. It is then obvious that 115 the distances from the horizontal and vertical axes through h to the bars g' and f' , respectively, will represent, to properly selected scales which take into account the constants in the formulae, the quantities θ and P .

The radial setting of pin e requires mechanism which will be taken up more specifically. Instead of the slot c , shown for sake of simplicity in Fig. 35, the straight line movement (actually used) is represented in Fig. 36. This movement consists of an arm i connected to shaft i' journaled in the sector b and to the midpoint of a lever k carrying projecting pins k' and e' , the pin k' having a backward extension arranged to be guided by slot k^2 formed by members k^3 attached to the 120

sector b , and the pin e' having a backward projection engaging in the slot h^4 formed by members k^5 and a forward projection which engages in vertical and horizontal parallel motion bars such as shown in Fig. 35.

The purpose of the slot c in Fig. 35 is to guide the block having the pin e radially of the axis h ; and it is obvious that the straight line movement of Fig. 36 will accomplish the same purpose, the pin e' moving along the dotted line shown between the limits c' and c^2 . This movement is caused by revolution of arm i keyed to shaft i' and to the latter there is also keyed, below the sector b , a scroll wheel i^2 . Scroll wheel i^2 is actuated by scroll wheel h' freely mounted on the shaft h to which the sector b is keyed. With this arrangement, any relative rotary movement between the sector b and the scroll wheel h' will cause the pin e' to move back or forth along the line c' — c^2 . By properly designing the scroll wheels, any mathematical law may be made to exist between the angular position of scroll wheel h' in relation to the sector b on the one hand and the radial distance from pin e' to shaft h on the other.

In Fig. 37, I show means for imposing from outside connections a definite angular relation between the sector b and the scroll wheel h' which shall be independent of any movement of the sector b due to the pinion a . In this view, the sector b , the arm i , the shaft i' and the scroll wheels i^2 and h' are designated similarly and correspond to Fig. 36. In Fig. 37, the shaft h is supported by fixed bearings h^2 and h^3 . Scroll wheel h' , loose on shaft h , is integral with the spider l carrying planet pinions l' engaging the long sun gear l^2 and the orbit ring l^3 . The sun gear l^2 is free to rotate on the shaft h and the orbit ring l^3 fits in the fixed ring m in which it may be adjusted manually, as later set forth, but otherwise it remains stationary. The sun gear l^2 also meshes with planet pinions l^4 , carried by a spider l^5 keyed to shaft h . The orbit gear l^6 meshing with pinions l^4 is integral with the large spur gear m' .

With this arrangement, the angular relation between the scroll wheel h' and the sector b will depend upon the angular position of gear m' , assuming orbit ring l^3 to be fixed; and, if the orbit ring l^3 is moved in its ring m , it will counteract a similar rotation of the gear m' , so that the net rotation becomes the rotation of m' minus that of l^3 which determines the angular rotation between the scroll wheel h' and the sector b .

$\log_{10} R_g$ is furnished to gear m' so that the angular position of this gear represents this logarithm. The ratio of orbit gear l^6 to sun gear l^2 is such that one turn of the spider represents a suitable $\log_{10}$ difference. $\log_{10} R_g$, that is, $\log_{10} R'$ corrected for parallax, would be supplied to the gear m' from the range

logarithm rim 458 having a gear 459 meshing with gear 565M' (see Fig. 16).

At the time the base line is laid out and the telescopes set up, the length G is measured; and this quantity, which is constant until the apparatus is moved, is set on the apparatus by turning orbit ring l^3 in fixed ring m which is graduated according to the logarithm of G to the scale of one turn of the ring l^3 equal a difference in $\log_{10}$ of G of a suitable amount. It is arranged that G can vary between desired limits, for example, from 150 to 300 feet.

The rotation of the function wheel h' is equal to $\log_{10} G - \log_{10} R_g = \log_{10} \frac{G}{R_g}$. The shape of the function wheels h' and i^2 is such as to cause pin e' (Fig. 36) to move so that the distance from the axis of shaft h to that of pin e' equals $\frac{G}{R_g}$.

In Figs. 38 and 39, I show the actual parallax apparatus employed. Here the orbit ring 565 l^3 has attached to it an arm 566 for the purpose of turning it conveniently. This arm carries at its outer end an index mark reading on the scale 567 and a clamp 568. The pins 565 e' and 565 k' are provided with small rollers for working in the slots 565 k^2 , 565 k^4 , 565 f and 565 g . The other parts of the apparatus, other than those specifically mentioned below, are similar to those already explained with respect to diagrammatic views 34 to 37, inclusive, and corresponding parts in Figs. 38 and 39 have reference characters combining "565" with the alphabetical characters used in Figs. 34 to 37, inclusive, so that all of the preceding descriptive matter pertaining to the latter views may be readily applied to Figs. 38 and 39 merely by considering the alphabetical suffixes of the latter views.

The ends of parallel motion bar 565 g' whose vertical displacement is equal to ρ , the correction to range, are fastened to the tape 570 at points 571 and 572, one of the clamping screws 573 being visible. The tape 570 is stretched over the sheaves 574, 575, 576, 578, 579 and 580 and the ends designated 441 and 441' pass to the tape wheel for adding the parallax correction to $\log_{10} \frac{R^1}{R_0}$ or to $\log_{10} R'$.

In a similar manner horizontal displacement of the bar 565 f' actuates a tape 581 passing about the sheaves 582, 583, 584, 585, 586 and 587 and such tape transmits the correction θ to the secondary angle ρ' to the transformer of coordinates apparatus.

The angle ρ' is transmitted to the apparatus from the shaft 487 which supplies ρ' to multiplier M6, while $\log_{10} R_g$ comes from rim 458 to the gear 565M'.

The transformer of coordinates device is shown in Figs. 10^b, 40, 41, and 42. Its object is to transform α with the ϕ correction added and ρ with the ψ correction added, that is ρ' ,

and the latter further corrected for parallax by adding θ , respectively, into azimuth and vertical angles, which, after further correction in the ballistic mechanism, are transmitted to the gun. In other words, the transforming apparatus converts coordinates to the azimuth and vertical system, so that the mechanical calculations may be utilized in laying a gun.

- 10 The transformer consists essentially of an outer member movable about a fixed or primary axis and an inner member movable with respect to the outer member about a secondary axis perpendicular to the first axis. The outer member is, therefore, movable about a single axis, whereas the inner member is not only movable about that axis but also another axis which is normal to the first. The inner and outer members constitute an "input" system, the outer member receiving the primary angle (α') and the inner member receiving the secondary angle (ρ' corrected for θ) and hence a point on a tertiary axis normal to the secondary axis and passing through 25 the point of intersection of the primary and secondary axes may be caused to point to any position in the heavens in accordance with the settings of the primary and secondary axes.

The "output" system consists of a first member movable about a vertical or quarternary axis which passes through the point of intersection of the primary, secondary and tertiary axes and a second member which is mounted to swing with respect to the first member about a quinternary axis which is normal to the quarternary axis and which passes through the point of intersection of the axes. Hence it will be apparent that a sexternary axis normal to the quinternary axis and passing through the point of intersection of the axes may be directed toward any point in the heavens according to the angular settings about the quarternary and quinternary axes. It only remains to connect the inner member of the "input" system and the second member of the "output" system so that the tertiary and sexternary axes coincide, in order that the first member of the "output" system may be caused to move in azimuth and the second member caused to move in elevation.

Referring now to Fig. 40, the "input" system consists of an outer frame member 590 pivoted about a primary axis $x-x$ with respect to stationary supporting structure 591 having bearings at 592 and 593 for this purpose. The inner frame member 594 nests within the outer frame member and the contours of these frame members are approximately spherical so that the "output" system may be arranged within the inner frame member and be operable therefrom. The inner frame member 594 has arms 595 which are pivoted to arms 596 of the outer frame member so that the inner frame member may

swing about a secondary axis $y-y$ normal to and intersecting the primary axis $x-x$. The inner frame carries a third arm 597 which has a tertiary axis $z-z$ movable about the secondary axis $y-y$.

The "output" system consists of a vertical stationary post 598 to which is pivotally mounted the first member 599 of the "output" system movable about a vertical or quarternary axis $w-w$ and a second U-shaped member 601 whose ends are pivotally connected to vertical ear portions 602 and 603 on lateral projections 604 and 605 carried by the first member 599. In this way, the U-shaped member 601 is mounted to swing about a horizontal or quinternary axis $v-v$, the U-shaped member having pivots 606 and 607 whose axes are coincident with this axis. The second member of the output system, namely, the U-shaped member 601 has a pivot 608 whose axis is coincident with tertiary axis $z-z$ which fits a bearing 609 in the arm 597 of the inner frame member, the axis of the bearing also being coincident with the tertiary axis $z-z$. The axes $x-x$, $y-y$, $z-z$, $w-w$, and $v-v$, all intersect at a common point. From the structure described, it will be apparent that the tertiary axis $z-z$ may be directed toward a given point by moving the outer and the inner members 590 and 594, respectively, according to any suitable system of coordinates, and that the necessary movement of the bearing 609 to direct the tertiary axis $z-z$ results in movement of the second member 601 of the "output" system in the vertical and movement of the first member 599 of that system in azimuth. The two members of the "output" system are connected to transmit vertical and azimuthal angles in a manner to be described.

Referring to Figs. 10^b and 40, the angle α is transmitted from α shaft 136 by sprocket gearing 613 to the shaft 560, which is connected to the sun gear 614 of the addition differential, at 615. The orbit gear 616 is carried by the tape wheel 558 which moves as ϕ . Hence the spider 617, carrying the planet pinions 618, will move as $\alpha+\phi$, or α' , which angle is transmitted by the gear 620 connected to the spider meshing with the sector 621 having a hub portion 622 fitting in the bearing 593 and connected to the outer frame 590 so that the latter is turned about the axis $x-x$ in accordance with α' .

Angle ρ' is transmitted from shaft 485 by gear 623 to gear 624, which fits about a sleeve 625 having at its outer end the sun gear 626 of the differential, at 627. The orbit gear 628 is carried by the gear 624, and the planet pinions 629 are mounted on a carrier 630 connected to the shaft 631 passing through the sleeve member 625 and through the hub portion 622. The tape 581, representing θ , drives tape wheel 632, the latter having a bearing on the sleeve 625 and being provided with an

internal or orbit 633 meshing with the pinions 634. The pinions 634 are carried by the sector 621 and they engage a sun gear 635 fixed to the sleeve 625.

The shaft 631 has connected to its inner end 5 a bevel gear 636 meshing with the bevel gear 637 carried by shaft 638 mounted in bearings 639 carried by the frame 590. The shaft 638 has connected thereto a pinion 641 meshing with the gear 642 to which is connected the 10 pinion 643 meshing with the gear 644 carried by the inner frame member 595.

From the arrangement of gearing referred to, it will be apparent that α' may be applied to the frame 590 without, in consequence, 15 causing any movement of the inner frame member 595 about axis $y-y$ for the reason that the shaft 631 turns with the frame 590 about the axis $x-x$, the pinions 629 resulting in turning of the sleeve 625 in the same direction as the shaft 631 and in the same direction as it tends to be rotated by the pinions 634; and since the orbit gears 633 and 628, the sun gears 635 and 626, and the planet pinions 634 and 629 are, respectively, the same size, when 20 the sector 621 turns, thereby rolling the pinions 634 on the orbit gear 633, the sun gear 635 moves at a peripheral speed equal to that of the pinions and in the same direction, 25 with the result that the outer frame 590 is free to turn without causing movement of the inner frame member 595 about its axis.

The parallax correction θ is transmitted to the orbit gear 633 while ρ' is applied to the 30 orbit gear 628 of the differential, at 627, with the result that ρ' and θ are added, becoming ρ'' which is transmitted by the planet pinions 629, the carrier 630, the shaft 631, bevel gears 636 and 637, shaft 638, and gears 641, 642, 40 and 643 to gear 644 carried by the inner frame 595, resulting in turning of the latter about the axis $y-y$.

Motion of the first member 599 of the "output" apparatus about the quarternary axis (vertical) $w-w$ and of the U-shaped or "second" member 601 of that apparatus correspond to the desired transformation azimuth (ν) and vertical (η) angles. These angles are transmitted to the ballistic apparatus by suitable telemetric devices. For example, in order to transmit ν I show the member 599 provided with an azimuth gear 645 which drives the telemotor, at 646, which transmits rotatational motion to the ballistic mechanism proportional to ν . The telemotor, at 646, is carried by a stationary part of the structure. To transmit η , I show a telemotor at 647, which is supported by the first member 599 of the "output" system and which is actuated through gears 648, 649, the shaft 650 and the gear 651, the latter being turned by the sector 652 carried by the U-shaped member 601.

In setting up the apparatus, the axis $x-x$ (Fig. 41) should be aligned with or parallel

to the base line. At the same time, the post 598 must be vertical. Hence I show the post 598 having a bearing shoe 655 with a lower convex bearing face whose axis is horizontal and passes through the point of intersection 70 of the aforesaid axes. The bearing surface 656 fits a concave seat 657 carried by the stationary structure 591. Any suitable means may be employed for moving the shoe 655 relatively to the seat. For example, (see 75 Fig. 42a) I show an arcuate rack 658 carried by the shoe and which meshes with a pinion 659 carried by a shaft 660, which has a worm wheel 662 meshing with a manually actuated screw or worm 663. If the base line should 80 be inclined, the screw 663 may be actuated manually to bring the post 598 into the vertical.

As the transformer of coordinates device is purely a mechanical arrangement, its absolute orientation is of no importance and it is, therefore, to be understood that the terms "vertical", "horizontal", and "parallel to the base line", as applied to that device in the 85 foregoing description are used to simplify an 90 understanding thereof.

The ballistic mechanism receives the vertical angle η from the transformer of coordinates device and $\log_{10} R_g$ from the prediction mechanism and from these, and other factors added to the mechanism, the following 95 factors are calculated:

(1) The square root of the time of flight $\sqrt{T}$, which is transmitted to the comparators 100 by the shaft 143 aforesaid;

(2) The angle of super-elevation "s", that is, the difference in vertical angle between the angle of departure and the future line of sight; and,

(3) The drift "d", the correction to 105 azimuth for this effect.

The time of flight $\sqrt{T}$ is found from the following factors:

(1) The logarithm of the future range 110 $\log_{10} R_g$ coming from the prediction mechanism;

(2) The vertical angle " η " coming from the transformer of coordinates; and,

(3) The tenuity " t " of the atmosphere, 115 found by meteorological observations and set on a handle provided for that purpose.

The solution for $\sqrt{T}$ is carried out in three steps:

First—Finding from $\log_{10} R_g$, obtained in 120 the prediction mechanism, the value of $\sqrt{T}$ for standard conditions and horizontal line of fire and here designated as $\sqrt{T}_0$;

Second—Finding the correction $\sqrt{T}_c$ to be 125 added to $\sqrt{T}_0$ to obtain $\sqrt{T}$ for standard conditions and inclined line of sight; and,

Third—Finding the correction $\sqrt{T}_a$ for atmospheric conditions to be added to $\sqrt{T}_0$ $\sqrt{T}_c$, 130 to obtain $\sqrt{T}$.

The corrections $\sqrt{T_n}$ and $\sqrt{T_t}$ are both small.

The mechanism for finding $\sqrt{T_0}$ consists of the tape 462 driven by the rim 458 for driving the tape wheel 665 carried by the shaft 666 of the ballistic mechanism (see Fig. 43) so that the latter moves angularly in proportion to $\log_{10} R_g$. The shaft 666 is connected to a scroll wheel 667 driving the scroll wheel 668 keyed to the shaft 669, the scroll wheels being so cut as to convert $\log_{10} R_g$ into $\sqrt{T_0}$ for standard conditions and a horizontal line of sight. The shaft 669, representing $\sqrt{T_0}$ is connected to the spider of addition differential, at 670.

For the purpose of finding the correction $\sqrt{T_n}$, I show a cam roller 672, so shaped that its axial motion corresponds accurately to $\sqrt{T}$ while its rotational motion corresponds accurately to η . The cam roller is rotatable and slideable with respect to a sleeve 673, the latter being rotated by sprocket gearing 674, driven by the train of gears 675, 676 and 677, the latter being connected to the shaft 678 of the servo-motor 679, which receives the vertical angle η from the telemotor 680 electrically connected to the telemotor 647 of the transformer of coordinates device. The accurate value of $\sqrt{T}$ comes from $\sqrt{T}$ shaft 143 through spiral gearing, at 681, which drives the screw shaft 681', constituting a support for the sleeve 673 and whose threaded portion 682 engages a nut member 683 having a post 684 passing through a longitudinal slot 685 in the sleeve, whereby, upon turning of the shaft 681, the cam member 672 may be traversed axially of the sleeve 673 in accordance with $\sqrt{T}$.

The roller cam member 672 is provided with two cam portions at 686 and 687, the portion 686 being used for the vertical angle correction, the one now immediately under consideration, and the cam portion 687 being involved in the tenuity correction considered later.

A follower roller 688 (similar to the roller 688' shown below) engages the cam portion, at 686, and imparts motion to the shaft 689 corresponding to $\sqrt{T_n}$. The latter shaft carries a sector 691 engaging a gear 692, which is the sun gear of the addition differential, at 693. The follower 688 is constrained to engage the cam portion of 686 by a spring 694.

Considering next the step of finding $\sqrt{T_t}$, this is determined by the follower 695 which engages the cam portion of 687, and which is carried by the shaft 696 with which cooperates a spring 697 to maintain engagement of the follower with the cam portion. The shaft 696 is connected to the arm 698 having an adjustable crank pin 700 (see Fig. 44), which engages in the slot 701 provided in the frame 702 and constrained to move as shown in Fig.

44 by the guide rollers 703 and by the gears 704 and 705, which may be selectively clutched to the shaft 706 for driving the orbit gear 720 of the addition differential, at 693.

The swinging of crank arm 698 imparts reciprocatory motion to the frame 702 and the extent of reciprocation may be varied by adjusting the position of the crank pin 700 with respect to the arm 698. To this end, I show the pin 700 carried by a block 708 which is traversible in the longitudinal slot 709 of the arm 698 by means of a screw 710 connected to a bevel gear 711, the latter meshing with a bevel gear 712 which may be turned by the hand crank 713.

The gears 704 and 705 mesh, respectively, with racks 714 and 715, and are rotated in opposite directions to the extent of the reciprocation of the frame 702. Either of these gears may be clutched to the shaft by a clutch mechanism which is similar to that shown in connection with the gears 704' and 705' of similar mechanism for actuating the shaft 706'. Here the gears are provided with key slots 716' and 717' engageable alternatively by a key 718' movable axially of the shaft 706' by the knob 719'.

The arm 698 is graduated in percentages of tenuity different from a standard; and, therefore, knowing the percentage the tenuity is off, the block 708 is adjusted longitudinally of the slot by turning the crank 713 until it reaches a position determined by the existing tenuity. If the tenuity factor is negative rather than positive with respect to standard, hand crank 713 is turned to bring the block 708 with the axis of the pin 700 aligned with the axis of shaft 696 which will bring the frame 702 and the shaft 706 to zero position, whereupon the clutch key 718 may be moved to engage the other gear in order that the negative value of tenuity may be read off on the scale previously used for positive values. The angular position of shaft 706 obtained in this manner represents the correction $\sqrt{T_t}$ to be added to correct for tenuity.

Having now obtained $\sqrt{T_0}$, $\sqrt{T_n}$, and $\sqrt{T_t}$, these values are added, $\sqrt{T_n}$ going to the sun gear 692 of the differential, at 693, while $\sqrt{T_t}$ goes to the orbit gear 720 of that differential. The planet pinions of this differential are carried by a spider connected to the shaft 721 so that the angular position of the latter represents $\sqrt{T_0} + \sqrt{T_t}$. The shaft 721 applies the latter quantity to the orbit gear 722 of the differential at 670, the value $\sqrt{T_0}$ being applied to the planet pinions thereof, with the result that the sun gear 724 thereof is rotated as $\sqrt{T_0} + \sqrt{T_n} + \sqrt{T_t}$ or $\sqrt{T}$.

The gear 724 is connected to a gear 725 meshing with a pinion 726 carried by the control shaft 727 of the servo-motor 728 whose driven gear 730 meshes with the pinion 731 keyed to the shaft 681.

The super-elevation S is determined by apparatus similar to that already described for determining $\sqrt{T}$, with one additional complication. It is not possible, as was the case with $\sqrt{T}$, to find from $\log_{10} R_g$ alone a value for the super-elevation which will apply to all cases for this range with only small corrections for vertical angle and tenuity. It has been found, however, that the cosine of the vertical angle times the value S_0 (which is the exact value of the super-elevation for horizontal range) is a good approximate value which can be made strictly accurate by small corrections.

15 The super-elevation will then be made up of three factors as follows:

$$S_0 \cos \eta + S_n + S_t = S,$$

20 where S_n is the small correction which must be added to the approximation, $S_0 \cos \eta$ to give the correct superelevation for the particular value of η involved, and S_t is the small correction which must be made for differences in atmospheric conditions.

25 The scroll wheel 733 on $\log_{10} R_g$ shaft 666 drives the scroll wheel 734, the scroll wheels being so cut that the wheel 734 represents $\log_{10} S_0$. See Fig. 45 for an outline of scroll wheels suitable for this purpose. The wheel 30 734 is connected to the orbit gear 735 of the differential, at 736.

35 The gear 675 driven from η servo-motor is connected to a sleeve 737, which has keyed thereto a scroll wheel 738 for driving the scroll wheel 739, the scroll wheels being so cut that the wheel 739 represents $\log_{10} \cos \eta$. See Fig. 46 for the scroll wheels. The latter wheel is connected to the sun gear 740 of the differential, at 736. The planet pinions 741, 40 therefore, through the spider 742, drive the shaft 743. The spider 742 and the shaft 743, therefore, represent the addition of $\log_{10} S_0$ and $\log_{10} \cos \eta$ that is $\log_{10} (S_0 \cos \eta)$. The shaft 743 carries a scroll wheel 745 which 45 drives a mating scroll wheel 746 keyed to the shaft 747, the scroll wheels being so cut that wheel 746 represents $S_0 \cos \eta$. See Fig. 47.

50 The quantities S_n and S_t are found by similar mechanism operating in the same way as that for finding $\sqrt{T_n}$ and $\sqrt{T_t}$. The quantities S_n and S_t are added in the differential, at 693', and the sum is then added to $S_0 \cos \eta$ 55 in the differential, at 670', so that the gear 750 represents $S \cos \eta + S_n + S_t$, or S , the gear 750 meshing with the gear 751 on the shaft 752 having a gear 753 thereon meshing with gear 754 carried by the receiving telemotor 680 connected to the η sending telemotor 647 of the transformer of coordinates device. It will, therefore, be apparent that the received angle η is corrected both for tenuity and time of flight, the corrected angle being transmitted by the servo-motor 679 both through

the gear 677 to the sleeves of the cams 672 and 672' so that the latter are turned as corrected η . Corrected η is transmitted from the shaft 678 by means of the sending telemotor 755 to the gun vertical angle receiving 70 telemotor 33. Adjusting means is provided at 756 to take care of windage.

75 In ballistic calculations, the angle of drift is frequently considered as directly proportional to the time of flight. In this apparatus, the somewhat broader assumption is made that it is a function of the time of flight. The apparatus for determining this correction is shown in Fig. 48 and it consists of a shaft 755 driven as $\sqrt{T}$ through gears 756 and 757 operated from $\sqrt{T}$ shaft 143. The shaft 755 has a pinion 758 thereon meshing with a gear 759 carrying the scroll wheel 760, which drives the scroll wheel 761, the scroll wheels being so cut, as may be seen from Fig. 48, that the wheel 761 represents the drift angle "d". This angle is transmitted through the gears 762 and 763 to the sending telemotor 764, connected by the conductors 80 to the azimuth receiving telemotor or follow-the-pointer device 32 at the gun. The sending telemotor is driven by a servo-motor 765, which, in turn is controlled by the receiving telemotor 766 connected electrically to the sending telemotor 646 of the transformer of coordinates. In this way, the azimuth angle γ is corrected for drift, the latter being a function of the time of flight, before being transmitted to the gun station. A manually operated shaft 777 has a pinion 90 778 thereon meshing with a gear 779 on the receiving telemotor 766 in order that wind corrections may be made.

100 The ballistic mechanism, therefore, receives $\log_{10} R_g$ and angles η and γ from which, and from manual settings for tenuity, it mechanically and continuously finds $\sqrt{T}$ for inclined sight, which quantity is transmitted continuously to the gun and to the comparators, the transmission to the gun being electrical by electric telemetric means through the conductors 34 (see Fig. 1). The azimuth and vertical angles are transmitted in the manner already set forth.

115 Electrical telemetric devices are interposed between the telescopes and between the latter and the gun. Fig. 52 shows one of these devices diagrammatically. In this view, the bipolar rotors A have windings A' in the common circuit A² connected by leads A³ to a source of alternating current. The rotors A are cooperatively related to fields B which have similar 120° points connected by conductors B', B², and B³.

120 Either of the telemotors consisting of a bipolar rotor A and a field B may be the sending telemotor while the other is the receiving telemotor. If one rotor A is turned angularly a given extent, the other, or receiv-

ing, rotor A will turn to the same extent. Corrections may be made by adjusting the fields. For example, the telemotors 680, 755, and 766 are provided with such correction devices, the field to telemotor 680 being adjusted by the adjusting gear 754 while the fields of the telemotors 755 and 766, are shiftable by the manual devices 756 and 777.

Referring to the modified form of my invention shown in Fig. 51, the telescope operator (or operators) at the near station in following the target rotates the telescope 801, by means of handles 802 and 803, representing the angles α and ρ respectively. The angle α is through direct shaft connection 804, conveyed to the α comparator 805, and also to the differential 806, shaft 807 being a continuation of 804. Through shaft 808, angle ρ (approx.) is conveyed to the differential 809, in which a correction proportional to α is added so that shaft 810 represents angle ρ free from the inaccuracy due to the rotation of the instrument frame. This shaft actuates comparator 811 and its continuation 812 enters the range and prediction mechanism while a further continuation 813, actuates one element of differential 814.

The angle ρ is also directly measured by means of selsyn, 815, on the telescope frame, the rotation being conveyed to electrical differential 816. This differential also receives the angle ρ_1 from the far station telescope 817, the target being followed by rotating handle 830 and the angle transmitted by selsyn 818. The pointer 819 of differential 816 reads the difference $\rho_1 - \rho = \lambda$ which is followed by a manual operation of handle 820, so that shaft 821 represents λ . This actuates the λ comparator 822 and through its continuation 823 enters the range and prediction mechanism.

The angle ρ_1 , transmitted by selsyn 818, is also received by selsyn 824 which, through servo-motor 825, actuates shaft 826 entering the range and prediction mechanism.

The quantities $V\alpha$, $V\rho$ and $V\lambda$ are the rates of change of α , ρ and λ respectively, each multiplied by the quantity T , the time of flight, found in the ballistic mechanism and sent back to the comparator by shafting 826, the comparator being so designed as to measure these composite quantities directly. Servo-motors 827, 828 and 829 read the comparators and actuate shafts entering the range and prediction mechanism.

The range and prediction mechanism receives all the quantities mentioned above and in addition B and G , the true length of the base line and the distance from the near station to the guns, these being set up on the handles shown. From all these quantities it continuously computes the corrections δ and θ which must be added to α and ρ to convert these angles of present position into the angles α' and ρ' , the correspondingly meas-

ured angles from the guns to the position the target will occupy after an interval, T , the time of flight of the projectile. It also computes the inclined range, R' , from the guns to the future position of target.

By means of the differentials 806 and 814 corrections δ and θ are added to the angles α and ρ to give α' and ρ' which latter enter and actuate the transformation of coordinates device. This piece of apparatus converts the angles α' and ρ' to spherical coordinates of the target measured on a sphere of reference with its polar axis in the line of the base line, into the angles γ_0 and η_0 measured on a sphere with its axis vertical, these angles being therefore azimuth and vertical angle. As the base line may not be actually horizontal it is necessary to set the crank β manually to the actual inclination of the base line to the horizontal. These selsyns, 835 and 836 transmit the angles γ_0 and η_0 from the transformation of coordinates device to the electrical differentials 837 and 838. In addition selsyn 835 actuates selsyn 839 which, in turn, through servo-motor 840, actuates shaft 841 entering the ballistic mechanism, the angular position of this shaft representing η_0 .

The future range R' , the vertical angle η_0 and the tenuity of the atmosphere (the latter set on handle t) enter the ballistic mechanism, which computes from these the time of flight, T , of the projectile, the drift correction, d , to γ_0 and the super-elevation correction, S , to η_0 . As the time of flight is found by apparatus which is not powerful enough to move the mechanisms to which the T shaft, 826 is attached, servo-motor 842, is employed to add power to this shaft. Selsyn 843 transmits T to the guns to govern the fuze setting, the time of flight dials at the guns being actuated by selsyns 844A, 844B, etc. The drift d , actuates the rotor of electrical differential 838, while super-elevation S actuates the rotor of electrical differential 837. The casings of these differentials are also capable of a small angular rotation by means of worm wheels and worms rotated by buttons W_a and W_v , for setting off azimuth and vertical angle wind corrections. The angular positions transmitted to selsyns 845A and 845B will, therefore, be the sum of the angles, γ_0 , S and W_v , while the angular position transmitted to selsyns 846A and 846B will be the sum of the angles η_0 , d , and W_a . These composite angles, designated η and γ are the correct angles by which to lay the gun. They are represented on dials at each gun position, a manually operated follow-the-pointer system being employed.

The angle ρ is transmitted from the telescope to the computing mechanism both electrically and mechanically. The mechanical transmission is necessary to furnish power for actuating the comparator and computing mechanism attached. The electrical trans-

mission might be omitted but it is thought that a more accurate value of the extremely important angle λ would result from the subtraction of ρ from ρ_1 if both these angles were brought to the differential mechanism by identical means.

The operation of apparatus utilizing my invention will be facilitated by reference to diagrammatic Fig. 53. Assuming the two telescopes are set up, the distance B between the telescopes and the distance G between the near telescope and the gun are measured, and the manual setting devices B and G on the prediction mechanism are set in accordance with those distances. Should the base line be inclined, the vertical post of the transformer of coordinates device is adjusted as hereinbefore set forth.

The telescopes have their primary axes aligned. Operators so move the telescopes as to train them on the target, such as an airplane. The primary angle α and the secondary angle ρ of the near telescope and the secondary angle ρ_1 are transmitted telemetrically to the computing machine, the angle α going to the comparators while the angles ρ and ρ_1 go to the range and position apparatus. The angle α is also transmitted to the transformer of coordinates device, and the angle ρ is also transmitted to the comparators and to the prediction apparatus.

The range and position apparatus subtracts ρ from ρ_1 to find λ and utilizes λ , ρ and ρ_1 in determining $\log_{10}R_0$, $\log_{10}(\cot \lambda - \cot \rho_1)$ and $(\cot \rho + \cot \rho_1)$, these quantities being transmitted to prediction apparatus. The quantity λ is transmitted to the comparators.

The comparators receive the angles α , ρ and λ and the quantity $\sqrt{T}$ from the ballistic apparatus and calculates mechanically $T \frac{d\alpha}{dt}$, $T \frac{d\rho}{dt}$, and $T \frac{d\lambda}{dt}$, which quantities are transmitted to the prediction mechanism.

The prediction mechanism receives the quantities mentioned from the range and position apparatus and from the comparators as well as the angle ρ from which it calculates mechanically $\log_{10}R_g$, the "future" secondary angle ρ' , ϕ the angle to be added to α to give the "future" primary angle α' , and θ the parallax correction to the secondary angle ρ' . The quantity $\log_{10}R_g$ is transmitted to the ballistic mechanism while ρ' , ϕ , and θ , go to the transformer of coordinates device.

The transformer of coordinates device first adds α and ϕ and ρ' and θ and transforms the respective sums into azimuth and vertical angles γ and η .

The ballistic apparatus receives γ and η from the transformer of coordinates apparatus and the quantity $\log_{10}R_g$ from the prediction apparatus. The ballistic mechanism has manual setting devices to take

care of atmospheric tenuity and wind. The vertical angle η is corrected for super-elevation and wind, and the azimuth angle is corrected for drift and wind. The quantity $\sqrt{T}$ for inclined fire is also found. Corrected values of η and γ are transmitted to the gun station while $\sqrt{T}$ goes both to the gun station and to the comparators.

From the foregoing it will be apparent that I have devised a fire control system or machine which receives angular motions of the telescopes, incident to training of the latter on a target, and thereby defines continuously three position-determining factors or coordinates and which utilizes mechanically these factors and the rates of change thereof found mechanically to concurrently and continuously find coordinates of future positions of a target, the latter coordinates preferably being the vertical and azimuth angles in accordance with which the gun is kept laid and the time of flight in accordance with which the gun is set. Assuming proper settings for length of base line, distance of the near telescope from the gun, atmospheric tenuity, and wind, it will be seen that the entire system is under control of the telescope operators, the azimuth and vertical angles for future target postions and the time of flight appearing at the gun station concurrently with training movements of the telescopes, thereby reducing the "dead time" to zero.

In connection with the telemetric transmission of angular motion, I prefer to make the telemotors relatively small and to use mechanical amplifiers wherever torques of any magnitude are required. In such an arrangement, the rotor of a receiving telemotor is connected to the control element of a servomotor. Also, the telemotors of the electrical transmission systems may be adjusted; for example, see the corrections for windage and the vertical angle correction. A servo-motor of the mechanical type which is capable of converting a small torque into a large torque and repeating or following the angular movement of the control element is shown in my application, Serial No. 5,327, filed January 28, 1925.

As hereinafter used the term spherical coordinates is taken to mean the system of locating a point in space by the use of two angles and a linear distance, one of the angles being the angle of rotational displacement about a primary or polar axis of the plane containing the point and the axis, from any arbitrary zero position of the plane; the other angle being the angle measured in the plane between the polar axis and the line connecting the origin and the point. The linear distance may be the true linear distance from the origin to the point or the projection of the distance on any specified plane. By the term ballistic spherical coordinates is meant the

spherical coordinate system in which the polar axis is the vertical, in other words the ordinary system of azimuth and vertical angle. The linear dimension may be horizontal range, inclined range, elevation, etc.

5. By the term special spherical coordinates is meant a spherical coordinate system with the polar or primary axis horizontal or inclined, but not vertical.

10 While I have shown my invention in two forms, it will be obvious to those skilled in the art that it is not so limited, but is susceptible of various other changes and modifications without departing from the spirit thereof, 15 and I desire, therefore, that only such limitations shall be placed thereupon as are imposed by the prior art or as are specifically set forth in the appended claims.

Having thus described the invention, what 20 I claim as new and desire to secure by Letters Patent is:

1. In a fire control system, the combination of mechanism to receive instantaneous position determining factors of a moving aerial 25 target, and from such factors and characteristics thereof mechanically and simultaneously to calculate factors determining a future target position, and means for transmitting the future position determining factors 30 from said mechanism.

2. In a fire control system, a machine for determining factors of future positions of a moving aerial target by which to lay a gun so that a projectile and the target shall reach 35 substantially the same position in space simultaneously comprising means for continuously receiving movements corresponding to the instantaneous values of position factors of the target, means for effecting 40 movements proportional to the rates of change of the factors times a function of the time of flight, and means for concurrently correlating the movements of said means to determine the factors for future positions of 45 the target.

3. In a fire control system, the combination of means movable in accordance with instantaneous position-determining factors of a moving aerial target, means operated by the 50 first means for determining quantities proportional to the rates of change of the instantaneous factors times a function of the time of flight, means operated by the first two means for concurrently determining the time 55 of flight to a future position and for determining two other future position-determining factors, and means for transmitting from the last named means to the product finding means a function of the time of flight.

60 4. In fire control apparatus, mechanism including means for receiving the instantaneous coordinates and means responsive to the instantaneous values of such coordinates and to quantities proportional to the rates of 65 change thereof for ascertaining coordinates

of future positions of the target, means for correcting the coordinates for parallax; and means for transforming the corrected coordinates into azimuthal and zenithal coordinates.

5. In mechanical fire control apparatus, mechanism for continuously ascertaining coordinates of future positions of the target including means for receiving instantaneous coordinates and means responsive to the instantaneous values of such coordinates and to quantities proportional to the rates of change thereof for ascertaining the coordinates of future positions of the target, two of the last named coordinates being spherical; 75 means for transforming the spherical coordinates into azimuthal and vertical angles; means for automatically correcting the azimuthal angle for drift; and means for automatically correcting the vertical angle for 80 super-elevation.

6. In a fire control apparatus, the combination with first and second telescopes having aligned primary axes, said telescopes being adapted to be trained on a movable aerial 90 target, of a mechanical system for automatically and continuously finding the difference between the secondary angles of the telescopes including mechanically actuated receivers, means for transmitting the secondary 95 angles from the telescopes to the receivers, and means for subtracting the secondary angle of the first telescope from the secondary angle of the second telescope.

7. In a fire control apparatus, the combination with first and second telescopes having aligned primary axes, said telescopes being adapted to be trained on a movable aerial target, of a mechanical system for automatically and continuously finding the logarithm 100 of the present range from the secondary angles of the telescopes, including members movable proportionally to the secondary angles, means operated from said members for subtracting the secondary angle of the first telescope from the secondary angle of the second telescope to obtain a derived angle, means for obtaining the logarithm of the sine of the secondary angle of the second telescope cooperating with the previously 105 mentioned means, means for obtaining the logarithm of the sine of the derived angle, and means cooperating with the previously mentioned structure for subtracting the second logarithm from the first to obtain the 110 logarithm of the present range.

8. In a fire control system, the combination of two spaced telescopes having aligned axes and adapted to be trained on a moving aerial target, three mechanically acting receivers, means for transmitting the primary and secondary angles of the telescopes to the receivers, means operated from the secondary angle receivers for subtracting one secondary angle from the other, means for obtaining 115 120 125 130

- the products of the rate of change of the primary angle, one of the secondary angles, and the derived angle times a function of the time of inclined flight, means for utilizing the four angles and the three products in determining the logarithm of the future range, and mechanism which utilizes said logarithm, the tenuity of the atmosphere, and the future vertical angle in determining the time of inclined flight.
- 5 9. In fire control apparatus, the combination of means adapted to be continuously trained on a moving aerial target, means for continuously transmitting spherical coordinates of the target consisting of one primary and two secondary angles from said first means, means for subtracting one secondary angle from the other secondary angle to obtain an angle of difference, the primary angle, 10 one of the secondary angles, and the angle of difference being further utilized as instantaneous spherical coordinates of the target, means for ascertaining primary and secondary angle corrections and adding such corrections to the instantaneous values of the last referred to primary and secondary angles and for ascertaining the future time of flight, means for adding parallax corrections to the time of flight ascertaining means and to the 15 corrected secondary angle, and means for converting the corrected primary and secondary angles into azimuth and vertical angles, respectively.
- 10 10. In fire control apparatus, ballistic mechanism including a rotary receiving element rotated in accordance with the logarithm of the range of a future position of a moving aerial target, a rotary receiving element rotated in accordance with the vertical 20 angle of a future position of a moving aerial target, a pair of connected cams of the combined axial and radial type, means for shifting the cams axially as a function of the time of flight, mechanical means for rotating the 25 cams as a function of the corrected vertical angle, followers cooperating with the cams, one of said cams being so cut that the resultant effect of axial and angular movements thereof is to impart to its follower a super-elevation correction corresponding to the vertical angle and the other of said cams being so cut that the resultant effect of axial and angular movements thereof is to impart to its follower a tenuity correction for super-elevation, mechanism operated by said followers for adding the corrections and the mechanism operated by the tenuity follower including mechanism whereby adjustments for tenuity conditions may be made, means for finding 30 the product of super-elevation for horizontal fire times the cosine of the vertical angle, means for adding said product and the vertical angle and tenuity corrections for super-elevation to obtain a resultant super-elevation correction for inclined fire, and means

for modifying the incoming vertical angle by the resultant super-elevation correction to obtain a vertical angle corrected for super-elevation.

11. In a fire control system, the combination, with means for determining the square root of the time of flight, of a friction disk, means for driving the disk proportionally to a variable angle, a shaft extending diametrically of the disk, a threaded shaft driven as the square root of the time of flight from said means, a friction wheel engaging said disk and splined to said shaft, a shifter for traversing the friction wheel and threaded to said threaded shaft, a driven member axially aligned with said shaft, a differential having bevel gears connected to the shaft and to the driven member and bevel pinions meshing with said bevel gears and carried by a carrier, a bevel gear on the friction disk, a bevel gear meshing therewith and carried by the carrier, a pivoted frame, a roller carried by the frame, a flexible connection between the driven member and the roller, a second roller arranged transversely of and engaging the first roller, a second friction disk geared to the second roller, a bevel gear carried by the second friction disk, a shaft extending transversely of the disk, a constant speed member, a differential including bevel gears carried, respectively, by the shaft and by the constant speed member and bevel pinions meshing with the bevel gears, a bevel gear connected to the carrier for the last-named pinions and meshing with the second friction disk bevel gear, a friction wheel engaging the second friction disk, a threaded shaft driven as the square root of the time of flight from said means, a shifter threaded to the latter shaft for shifting the last-named friction wheel, a motor, a pair of spaced contacts, a contact cooperating with the pair of spaced contacts and carried by said frame, all of said contacts being connected to the motor, and means operated by the motor to cause the pair of spaced contacts to follow the motion of said frame to open a circuit of the motor when the frame comes to a stop.
12. In a fire control system, the combination with means for finding the square root of the time of flight, of mechanism which receives the square root of the time of flight and a variable angle and drives a shaft proportional to the product of the square root of the time of flight times the rate of change of the angle, a pivoted frame, a roller carried by the frame, a flexible joint construction between the shaft of said mechanism and the roller, a constant speed motor, a second roller extending transversely of and engaging the first roller, transmission mechanism between the motor and the second roller, means operative from said time of flight means to cause said transmission mechanism to so operate that the second roller rotates propor-

tionally to the reciprocal of the square root of the time of flight, a second motor, a pair of spaced contacts, a third contact carried by the frame and adapted to engage either of the contacts of said pair when the frame swings, and means operated by the second motor to cause the pair of contacts to follow the motion of said frame and to open the circuit of said second motor upon the frame ceasing to swing.

13. In a fire control system, the combination, with means for finding the square root of the time of flight, of a friction disk driven proportionally to a variable angle, a driven shaft extending transversely of the disk, a screw shaft arranged parallel to the driven shaft and operated by said time of flight means, a friction wheel splined to the driven shaft, a shifter operated by the screw shaft, for moving the friction wheel, a pivoted frame, a roller carried by the frame, a connection including a flexible joint between the roller and said driven shaft, a constant speed motor, a driving shaft operated thereby, a friction wheel splined to the driving shaft, a friction disk driven by the friction wheel, a threaded shaft arranged parallel to the driving shaft, a shifter threaded to the threaded shaft for shifting the friction wheel, a second roller driven by the last-named friction disk, extending transversely of the first roller, and engaging the latter, a pair of spaced contacts, a third contact carried by the frame, a reversible motor connected to the contacts, and means operated by the motor to cause the pair of spaced contacts to follow the motion of said frame, whereby, when the latter comes to a stop a circuit for the motor will be broken.

14. In a fire control system, the combination, with means for determining the square root of the time of flight, means operative from a variable angle and from said time of flight means for moving an element proportionally to the product of the square root of the time of flight times the rate of change of the angle, a source of constant speed, mechanism operative from said source and from the time of flight means for moving an element proportionally to the reciprocal of the square root of the time of flight, division mechanism operative from the first and second elements, a servo-motor, and a controller for the servo-motor which is operated in accordance with the quotient of the division mechanism.

15. In a fire control system, the combination, with means for determining the square root of the time of flight, means operative from a variable angle and from said time of flight means for moving an element proportionally to the product of the square root of the time of flight times the rate of change of the angle, a source of constant speed, mechanism operative from said source and from

the time of flight means for moving an element proportionally to the reciprocal of the square root of the time of flight, division mechanism operative from the first and second elements, a reversible electric motor, a pair of spaced contacts and a third contact whose position depends upon the quotient of the division mechanism and which operates, upon a change in said quotient to complete a circuit for said motor, and follower up mechanism operated by the motor for moving the spaced contacts relatively to the third contact to open the motor circuit when the quotient ceases to vary.

16. In a fire control system, the combination, with means for finding the square root of the time of flight, mechanism which continuously determines the rate of change of an angle, means for continuously multiplying the rate of change by the square root of the time of flight, a swingably mounted friction roller which is rotated as said product, a second friction roller engaging the first roller transversely, a constant speed motor, means for modifying motion of the motor such that the motion is proportional to the reciprocal of the square root of the time of flight, means for transmitting said modified motion to the second roller, a servo-motor, and a controller for the servo-motor responsive to the swing of the first roller.

17. In a fire control system, the combination, with means for finding the square root of the time of flight, mechanism which continuously determines the rate of change of an angle, means for continuously multiplying the rate of change by the square root of the time of flight, a swingably mounted friction roller which is rotated as said product, a second friction roller engaging the first roller transversely, a constant speed motor, means for modifying motion of the motor such that the motion is proportional to the reciprocal of the square root of the time of flight, means for transmitting said modified motion to the second roller, a servo-motor, and a controller for the servo-motor comprising a contact which swings with the first roller, a pair of spaced contacts, and means operative from the servo-motor for causing the spaced contacts to follow the motion of the first roller.

18. In a fire control system, the combination, with means for continuously and mechanically determining the square root of the time of flight, of a friction disk driven proportionally to a variable angle, a frictional wheel engaging one face of the disk, means for traversing the wheel transversely of the disk, said traversing means being operable from the means for determining the square root of the time of flight, a constant speed motor, transmission means operated by the constant speed motor, means for imposing the effect of the square root of the time of flight

- upon the transmission means so that the final element of the latter rotates as the reciprocal of the square root of the time of flight, a roller driven by said transmission means, 5 a swingably mounted roller driven from the friction wheel and arranged transversely of and engaging the first roller, a servo-motor, and a controller for the servo-motor operated by the swing of the second roller.
- 10 19. In a fire control system, a multiplying device consisting of first and second driving members, a rocker member driven by the first member, a variable pitch screw carried by said rocker member and having its axis intersecting the axis of the latter, said screw being driven by the second driving member, a crank pin movable radially of the axis of said rocker member, and a parallel motion bar operated by said crank pin.
- 15 20. In a fire control system, the combination of a driving member, a rocking member, a crank pin carried by the arm, a link pivotally connected intermediately of its length to the pin, a guide whose axis intersects the axis of the rocking member, a guide member carried by one end of the link and fitting the guide, and a driven member connected to the other end of the link.
- 20 21. In a fire control system, a multiplying device consisting of first and second driving members, a rocker member, a screw carried by the rocker member and driven by the second driving member, a crank pin movable radially of the arm and traversed by the screw, and a member operated by said pin.
- 25 22. In a fire control system, a multiplying device consisting of first and second driving members, a rocker member, a screw carried by the rocker member, and driven by the second driving member, a crank pin movable radially of the arm and traversed by the screw, and a parallel motion bar operatively connected to said pin.
- 28 23. In a fire control system, a multiplying device consisting of first and second driving members, a rocker member, a screw carried by the rocker member and driven by the second driving member, a crank pin movable radially of the arm and traversed by the screw, a slotted bar engaging the pin, tape means connected to the ends of the bar to assure parallel motion of the latter, and a driven member operated by said tape means.
- 30 24. In a fire control system, a multiplying device consisting of a first driving member, a second driving member, a rocker member, a slotted bar, a screw operated by the second driving member for raising and lowering one end of the bar, a parallel-motion member, a roller carried by the last named member and engaging in the slot of said bar, a slotted guide having the axis of its slot intersecting the axis of the rocker member, a link pivotally connected intermediately of its length 65 to and eccentrically with respect to the axis of said rocker member, a pin carried by one end of said link and engaging in the guide slot, and a pin carried by the other end of the link and engaging the bar slot.
- 35 25. In a fire control system, computing apparatus for determining the logarithm of the future range $\log_{10} R'$, and telemetric means for continuously transmitting the primary angle α and the secondary angles ρ and ρ_1 to the apparatus, said computing apparatus comprising, means for subtracting ρ and ρ_1 to find the derived angle λ , means for determining the time of flight T and the primary and secondary angle corrections ϕ and ψ , 70 means for finding the quantity $\log_{10} [1 + T \frac{d\rho}{dt} (\cot \rho + \cot \rho_1) - T \frac{d\lambda}{dt} (\cot \lambda - \cot \rho_1)]$, 75 means for finding $\log \cos \phi$, means for subtracting $\log \cos \phi$ from said quantity, means for finding $\log \cos \psi$, means for finding $\log (1 + \cot \rho \tan \psi)$, means for adding $\log \cos \psi$ to $\log (1 + \cot \rho \tan \psi)$ to obtain the sum $\log \cos \psi + \log (1 + \cot \rho \tan \psi)$, and means for subtracting the latter sum from said quantity minus $\log \cos \phi$ to obtain $\log_{10} R' - \log_{10} R_0$. 80
- 85 26. In a fire control system, computing apparatus and means for transmitting the primary angle α and the secondary angles ρ and ρ_1 , said computing apparatus consisting of means for subtracting ρ from ρ_1 to obtain the derived angle λ , means for finding the time of flight T , means for obtaining the rates of change $\frac{d\rho}{dt}$ and $\frac{d\lambda}{dt}$, means for multiplying the rates of change by T , means for finding the cotangents of ρ and ρ_1 , means for adding the cotangents, means for finding $\log \sin \lambda$, means for finding $\log \sin \rho_1$, means for adding $\log \sin \lambda$ and $\log \sin \rho_1$, means for finding $\log \sin \rho$, means for subtracting $\log \sin \lambda + \log \sin \rho_1$ to obtain $\log (\cot \lambda - \cot \rho_1)$, means for converting $\log (\cot \lambda - \cot \rho_1)$ into $(\cot \lambda - \cot \rho_1)$ 90 means for multiplying the latter quantity by $T \frac{d\lambda}{dt}$, and means for subtracting $T \frac{d\lambda}{dt} (\cot \lambda - \cot \rho_1)$ from $T \frac{d\rho}{dt} (\cot \rho + \cot \rho_1)$. 100
- 95 27. In a fire control system, the combination with computing apparatus for finding future primary and secondary angles, means for transforming the angles into azimuth and vertical angles, comprising an input system consisting of an outer member movable about a primary axis in accordance with the corrected value of the secondary angle and inner member carried by the outer member and movable about an axis normal to the primary axis and an output system consisting of a first member pivoted about a quaternary axis which passes through the point of intersection of the primary and secondary axes and a secondary member pivoted to the first 105 110 115 120 125 130

- member about a quintary axis normal to the quaternary axis and passing through the point of intersection of said axes, and a pivotal connection between the inner member of the input system and the second member of the output system and whose axis is a tertiary axis normal to the quintary axis and passing through the point of intersection of said axes.
- 10 28. In ballistic mechanism for a fire control system, the combination of a cam which is movable axially as a function of the time of flight and angularly as the vertical angle, a follower cooperating with the cam, a tenacity correction element operated by the follower, and manual means for adjusting the angular motion of said element with respect to the follower.
- 15 29. In ballistic mechanism for a fire control system, the combination of a cam for correcting for tenuity of the atmosphere, said cam being movable axially in accordance with a function of the time of flight and angularly in accordance with the vertical angle, a pivotally mounted follower cooperating with the cam and an angularly-movable correction element.
- 20 30. In ballistic mechanism for a fire control system, the combination of a cam for correcting for tenuity of the atmosphere, said cam being movable axially in accordance with a function of the time of flight and angularly in accordance with the vertical angle, a pivotally mounted follower cooperating with the cam, an angularly-movable correction element, and manually controlled variable ratio motion transmitting means between the follower and said element.
- 25 31. In ballistic mechanism for a fire control system, the combination of a cam for correcting for tenuity of the atmosphere, said cam being movable axially in accordance with a function of the time of flight and angularly in accordance with the vertical angle, a pivotally mounted follower cooperating with the cam, an angularly-movable correction element, and manually controlled reversible variable ratio motion transmitting means between the follower and said element.
- 30 32. In ballistic mechanism for a fire control system, the combination of a cam of variable contour axially, said cam being movable axially as a function of the time of flight and angularly as the vertical angle, a follower for the cam, a crank shaft connected to the follower, a crank arm carried by the crank shaft, an adjustable crank pin carried by the arm, a reciprocatory member having a transverse slot engaging the pin, an angularly movable correction member, and means for converting reciprocatory motion of said member.
- 35 33. In ballistic mechanism for a fire control system, the combination of a cam of variable contour axially, said cam being mov-
- able axially as a function of the time of flight and angularly as the vertical angle, a follower for the cam, a crank shaft connected to the follower, a crank arm carried by the crank shaft, an adjustable crank pin carried by the arm, a reciprocatory member having a transverse slot engaging the pin, an angularly movable correction member, means for converting reciprocatory motion of said member in one direction into angular motion of the correcting member, and means for varying the position of said crank with respect to the axis of the crank shaft.
- 40 34. In ballistic mechanism for a fire control system, the combination of a cam of variable contour axially, said cam being movable axially as a function of the time of flight and angularly as the vertical angle, a follower for the cam, a crank shaft connected to the follower, a crank arm carried by the crank shaft, an adjustable crank pin carried by the arm, a reciprocatory member having a transverse slot engaging the pin, an angularly, movable correction member, means for converting reciprocatory motion of said member in either direction into angular motion in one direction or the other of the correcting member, and manual means for adjusting the position of the crank pin with respect to the axis of the crank shaft.
- 45 In testimony whereof I hereunto affix my signature.
- HENRY W. NIEMAN.
